RAILWAY CONTROL SYSTEM
Leonard D. Barry, 19300 Pennington Drive,
Detroit 21, Mich.
Filed Oct. 3, 1955, Ser. No. 538,058
62 Claims. (Cl. 104—18)

This invention relates to contact control systems and in particular to a railway system for coupling and uncoupling cars at operating speeds and for controlling speed differences between cars or trains whereby they can safely couple, uncouple, or closely follow each other at speed.

This is a continuation-in-part of my abandoned application Ser. No. 146,767 on Railway Control System for Coincident Local and Express Service and is directed toward the control circuits and improvements thereof.

The control circuit between trains described in the above mentioned application and disclosed in improved and various forms herein can be represented briefly as a circuit including a shunt or separately excited dynamo or other suitable voltage supply arranged on each of two or more vehicle units developing an output representing vehicle speed and connected in parallel by trackway conductive means between vehicles, and automatic accelerating and decelerating means on the vehicles arranged to accelerate or decelerate the vehicle respectively according to whether the vehicle's tachometric voltage supply device or dynamo in this circuit is functioning as a receiver or generator and according to the operator's direction, whereby the operator's control, or normal operating speed, is subject to conditions of safety and whereby the speed and various other functions for coupling and uncoupling at speed are controlled automatically.

The length of the control circuit between trains is limited by insulators and block circuits which control the bridging of the insulators so that the range or zone of the control always extends a safe distance ahead of or behind the train. Whenever this control circuit is completed between trains the trains are controlled to a safe speed difference.

An object of this invention is to provide a contact control system whereby a train can safely couple and uncouple cars at speed on the same stretch of track or anywhere along the trackway without the train being needlessly slowed. A further object is that these controls enable the train to accelerate a car or train ahead at the same time a car is uncoupled from the rear and slowed.

It is an object that the contact system distinguish an approaching from a receding train, so that when a car or unit is uncoupled from the rear of a train, for example, the unit can be slowed and stopped without causing the train to be slowed or without disrupting the control circuit and yet permitting the train and car to maintain control between other vehicles within the range of control. As another example, it is desired that trains in the same zone of control can be independently accelerated by the operator's controls either or both away from the other and maintain control with any vehicle they approach. It is an object to limit acceleration to the direction away from an approaching vehicle in the zone of control.

It is an object to provide a polarized control current to distinguish a faster moving from a slower or standing vehicle; and, if two directional operation is desired, to provide a polarized control voltage to represent direction of vehicle movement; and further, to polarize the transmission system of the control current to distinguish an approaching from a receding vehicle; and to polarize the vehicle's control circuits and, if two directional operation is provided, to connect these circuits through contacts on the vehicle's reverse switch to select proper control.

2

It is an object of this invention to polarize the control circuit between trains to provide signaling between trains traveling in the same direction when the faster moving train is in the rear and to block signaling therebetween when the slower moving train is in the rear.

In accord with this invention various rectifier or circuit polarizing arrangements are provided in the control circuit along the right-of-way or both along the route and on the vehicles. It is a further object to overcome any limitation which these polarizing arrangements may impose where it is desired that the speed of a rail unit be limited by a rail unit therebehind, so that the forward unit can be reached and coupled more readily or assuredly without running away.

It is an object to replace the stopping zone as disclosed in my above mentioned application with a control circuit having rectifiers arranged to limit the direction of control current along the control conductors between vehicles, so that only a slower forward and faster rearward train will pass a control current. The stopping zone, on the other hand, is a section of trackway where the control circuit is open between vehicles however close and requires for safety that the trackway be clear except for a train and a unit uncoupled therefrom.

If intertrain control circuits were completed on every car a train of one car approaching a train of ten cars would send a current and the cars of the other train would each receive approximately one-tenth of this current, or each car of a ten car train approaching a standing car at the same speed difference would each send approximately a tenth of the same current to the car. Thus the more cars in a train relative to the number of cars in a train in intercontrol therewith the smaller and less effective the control current would be on the larger train. It is therefore desired that just one intertrain control circuit per train be closed. Accordingly the control circuit is connected through the car's reverse switch and through coupling switches.

To prevent control between two cars when one uncouples from the other and each has its control circuit completed to a single control line, rectifiers are spaced between lengths of the control line at less than the interval between control circuit contact points between the two cars when coupled. It is a further object to reduce the number of these rectifiers or other polarizing means needed along the right-of-way by providing a period in which the control circuit on the uncoupled car or unit is fully or partially opened so that it will not receive signals from the faster moving forward train even when connected by the same section of the control conductor. It is an object to automatically slow a unit uncoupled at speed to increase the distance to the forward train to include a minimum of one rectifier in the control circuit between trains before the time interval of open control ends. Automatic slowing of an uncoupled unit when its control circuit is open is important. It is therefore a further object to provide safety means to check before uncoupling is permitted that there is no train within the zone of control that would not be in intercontrol where needed for safety. It is a further object to stop any traffic which after the unit is uncoupled might enter the zone of control at the rear of an uncoupled unit that does not receive control current, approaching traffic being stopped by signaling or by shorting the control conductors.

It is a further object to ground the control circuit of the control line conductor relative to all traffic approaching any danger condition or defective portion of the control circuit. Another object is to provide means to prevent a train from being automatically accelerated or from being accelerated at an unsafe speed toward a forward

train by an approaching rearward train. Some other objects of safety are to provide check circuits to detect a car that has no control circuit or an open control circuit to warn or stop approaching trains, to check the control circuit including important connections such as the bridging of the control blocks and electrical contact between the control conductors and current collectors on the vehicles, to stop a train whose control or check circuit is open or defective, and to warn or stop trains approaching a defective control block.

Another object is to arrange this intertrain control circuit to utilize a power distribution contact conductor for control signaling or, in other words, to arrange that the control line be suited as the power line for electric traction.

Another object is to provide control circuit arrangements for either insulated or noninsulated rails; so that advantage may be taken of existing track circuits, the trolley wire need not be divided into blocks, or the control circuit can be utilized even where rails are not insulated apart as in street-railway service. Variations are accordingly provided: one in which the rail and control conductor are both insulated into blocks or sections, others in which either only the rails or only the control line conductor are divided into blocks for limiting the zone of control between trains.

Some of the other and further objects are: to provide a contact control system to accelerate a car ahead of a train to coupling speed subject to the desire of the operator on the car ahead; to stop or slow a train to coupling speed before reaching a standing or slower moving car; to provide an optionally selectable delay of stopping when the intertrain control circuit is first completed with a strong stopping current and a continuous check of the reduction of this stopping current according to the distance traveled during the delay period whereby if the current does not reduce sufficiently the brakes are applied; to limit the magnitude of the control current so that the control current will not be excessive where large speed differences exist; and to dependability, safety, and convenience of operation.

A general object for these controls is to reduce needless automatic slowing of the train or car when conditions are safe.

These controls are such that they can be utilized for accelerating multiple unit cars ahead of a train of these cars to safely couple therewith at speed, to couple and uncouple cars on the rear of a train at speed, to prevent coupling or collision, and to control the speed of vehicles paralleling a train at speed to permit transfer therebetween. The word track is meant to include parallel tracks and control conductor to mean parallel and electrically connected control conductors where the controls are installed for speed control between vehicles on parallel vehicle ways.

All or a number of these and other objects are obtained in cooperation in the variations of this invention described hereinafter with reference to the accompanying drawings wherein:

FIGURE 1 is a diagrammatic view of a trackway along which are control-circuit and trackway blocks and differential check circuits each controlling a train stop and signal lamp, and on which a train and car uncoupled therefrom are shown with their intertrain control circuit.

FIGURE 2 is a diagrammatic view of control circuits on a multiple-unit car arranged to operate over the system illustrated in FIGURE 1.

FIGURE 3 is a perspective view of two of the operator's control levers showing interlocking therebetween.

FIGURE 14 illustrates how A.C. traction power can be supplied on a D.C. control conductor and separated on the trains.

FIGURE 15 is a diagrammatic view of a trackway, a train and an uncoupled unit thereon, and circuits of a two-control-conductor system for interrupting control between the train and unit while maintaining control with other trains within the zone of control.

FIGURE 16 is a diagrammatic view of more complete control circuits on a car of FIGURE 15 showing a variation of the speed controls over those shown in FIGURES 2 and 12.

Trackway Control Divisions and Bridging

Referring to the drawings and in particular to FIGURES 1 and 2, along track 10, FIGURE 1, having rails 11 and 12 is run control conductor or line 14. Line 14 is a rail or wire contact conductor insulated from ground and supported similarly as third rail or trolley wires in electric traction. All or a portion of line 14 can be divided into segments 16 by insulators 18. Multiple-unit cars 20, 21, and 22 on track 10 have current collectors or trolleys 24 engaging control line 14 connecting an intertrain control and a check circuit between line 14 and the rails. Segments 16 are shown shorter than the spacing between collector shoes or trolleys 24 on different cars when coupled. Adjacent sections or segments are each separated by a rectifier 26 arranged to pass a current from left to right from section to section along the control line 14. A series of segments are electrically connected to line 28 in which the rectifiers 26 which are between these segments are conveniently located with a condenser 30 across their terminals to pass an A.C. check current and a current for closing a two-way signal circuit.

Control blocks A and B, represented in FIGURE 1 each as a series of control line segments, and block C, which is not divided into segments, are arranged to be electrically connected or bridged together for a safe distance between trains. Block A is bridged to B and B to C etc. each through a rectifier 26 in series with an A.C. choke 32 and back contacts on either or both control-line-block bridging relays BR and BR1 the back contacts of which are in parallel. Similarly other blocks not shown are connected along the trackway. A rectifier connection between blocks or segments of blocks is called a rectifier bond.

Rail 12 is divided in the usual manner by insulators

36 into track circuit blocks A', B', and C' of substantially the same length and as part of control blocks A, B, and C respectively and displaced to the left relative to the control blocks equal to the distance from the engaged current collector to beyond the front wheel contact points on the vehicle on which this distance is greatest. Where line 14 is a third rail and trolleys 24 are shoes placed endward beyond contact points of the car wheels the control line blocks and track circuit blocks can be coextensive (no displacement needed). Across rails 11 and 12 at the left-hand end of each block a secondary coil 38 of supply transformer 40 is connected preferably as shown to supply reverse polarity on adjacent blocks. Across rails 11 and 12 at the right-hand end of each block the coil of a track circuit relay TR is connected.

Track circuit relays TR control the bridging relays BR and BR1 so that whenever the track circuit is shorted a number of control blocks either to the right or left or in both directions along the track are electrically connected together. Rail 11 being free from insulators is the return conductor for the control circuit between trains. If both rails have insulators the insulators can be bypassed by the usual impedance bonds or as shown in FIGURE 11 by rectifier bonds or by relay bridges across insulated track joints in one rail.

The coil of relay BR between blocks A and B is connected through a circuit comprising in series secondary 42 of transformer 40 block C', line 43 opened through front contacts 44 of relay TR in block B' and closed through front contacts 45 of relay TR in block A', and the coil of relay BR between blocks A and B to ground. Thus a car shorting the rails of block B' will drop relay TR therein dropping relays BR at each end of block B bridging control line sections A, B, and C together. Other blocks are similar to block B.

To increase the number of blocks bridged together upon shorting a track circuit block, each line 43 can be extended through other front contacts on relays TR in a series of adjacent blocks, whereby a solid group of blocks are bridged whenever a relay TR is dropped. To bridge blocks in the opposite direction from a train, secondary 42 of transformer 40 block B' is connected by line 46 through front contacts 47 of relay TR block A' to relay BR1 between blocks B and C. To increase the number of blocks bridged by line 46 this line can be extended to include one or more other front contacts on relays TR in a series of blocks, whereby a solid group of blocks are bridged in both directions from a shorted block. The zone of control between trains is limited by the maximum number and length of the blocks bridged together by the shorting of each track circuit block. Three to four blocks is the variation of the zone control between trains with the arrangement shown in FIGURE 1. Each extension of line 43 or 46 to include another pair of front contacts of the next relay TR is an additional block bridged by the shorting of a block.

Check Circuits

A.C. check circuits run from one end of one control block to the far end of the next block and include the bridge contacts between blocks to insure that the blocks are properly connected together. They also check the control line and control line grounding lines for breaks and shorts, check the control circuit on the cars and give warning or stop the train when not receiving check current, check if there is a car on the track having no automatic controls or open control circuit, and short the control line within the zone of control relative to traffic approaching a shorted or open track circuit block when either the A.C. check current of the control block associated with the shorted or open track circuit block or the adjacent control block to the left is not reduced by check current drained from the control line through one or more car control check circuits or when the check current is absent. The control line check circuit of block

B comprises in series coil 48 of transformer 40 in block B', the left-hand coil of differential relay DCR at the opposite end of block B', attenuator 50 arranged to block all but the check current to the output side of rectifier 52 between blocks A and B, back contacts of relays BR or BR1 between blocks A and B, line 28 block B and condensers 39 therein, segment 16 at the right-hand end of block B, line 52, attenuator 53 arranged to block all but the check current, coil of sensitive relay SCR, signal light 54 which indicates that the check circuit is completed, right-hand coil of differential check relay DCR, rail 12 to coil 48, all in block B'.

The intertrain control circuit between car 22 and train 20-21 comprises briefly on each unit trolleys 24 connected by line 56 between coupled cars, segment 57 of traction motor reverse switch REV connecting coupling switch SC closed on the front of car 22 and train 20-21, A.C. choke coil 58, resistor 59 across which current-direction-polarized automatic car controls ACC are connected through reverse switch 60 reversed when the cars are moving in the opposite direction on track 10, dynamo DYN developing a voltage representing car speed, all in series across control line 14 and the rails. This intertrain control circuit is similarly connected in parallel across line 14 and ground return rail 11 by each train having this control. The faster unit 20-21 generates a control voltage blocked by rectifiers 26 from passing current to car 22 uncoupled therefrom and slowed. If the faster unit were behind, the dynamo in the control circuit thereof would act as a generator supplying current to the dynamo of the slower unit operating as a motor. Automatic car controls ACC determine whether the dynamo is generating or motoring and according to the current provide safe and desired control automatically. Each car has an A.C. check circuit completed on each train across the control line and rails via the train's intertrain control circuit. The check circuit through each train, as shown in FIGURES 1 and 2, utilizes a portion of the trackway check circuit described and the portion of the train's control circuit to be checked by current in this circuit. The check circuit for either train of FIGURE 1 comprises coil 48 of transformer 40 block B', the left-hand coil of relay DCR at the opposite end of block B', attenuator 50, back contacts of relays BR and BR1 in parallel between blocks A and B, line 28 block B, trolley 24 of each train in block B, and on each train (referring to FIGURE 2) segment 57 of reverse switch REV, contacts 86 of coupling switch CS, line 88, line 62 from the trolley side of choke 58, back contacts of relay COR which is energized for a while after the car is uncoupled from a train, a series-parallel tuned circuit 63 arranged to pass the check current and block other frequencies, and full-wave rectifier 64 with the coil of check relay CR connected across its output terminals back to line 88 on the other side of choke 58, resistors 90 and 59 in line 88, dynamo DYN to rails 11 and 12 to the other side of coil 48 in block B. The opening of this A.C. check circuit by relay COR or otherwise, as by a broken wire or open trolley circuit, enables, as will be explained, a sole car or unit shorting a track circuit or adjacent track circuits to automatically stop approaching trains having the automatic controls of FIGURE 2. Track relays TR can also control a usual type of signaling for trains not having this automatic control circuit.

Control line sections are grounded and stop signals can be set whenever a check circuit indicates a dangerous condition. Block B is arranged to be grounded through line 52 above attenuator 53 to ground rail 11 through a circuit comprising in series A.C. choke 66, and either back contacts of relay SCR block B to rail 11 or in parallel back contacts of relay TR block B, back contacts of differential relays DCR of blocks B and A all in series to rail 11. The control line ground is similarly connected in other blocks. The inclusion of back contacts

7
of relay DCR block A together with the displacement of the track blocks relative to the control blocks prevents the shorting of the control line by a train extending into two blocks when drawing check current from only one of these blocks. Where line 14 is a third rail, for example, and all power vehicles have third-rail shoes engaging line 14 at both ends of the vehicle endward of the contact points of the wheels, the grounding lines for control line 14 need not be connected through back contacts of differential relay DCR in the block to the left of the shorted block but preferably only through back contacts of relays TR and DCR in the same block with line 52.

When there is no traffic near, relays DCR and SCR are deenergized, since the check circuit is opened by the energizing of both relays BR and BR1 between two blocks by the energizing of several track circuit relays TR in adjacent blocks. Then, as a train approaches, the control blocks are bridged ahead of the train by the dropping of relays BR or BR1 according to the direction of travel, closing check circuits, energizing relays DCR and SCR ahead of track circuit blocks shorted by the train. When a train whose check circuit is closed enters a control block the check current reaching relay SCR is reduced, but relay SCR remains energized and open, being designed to hold up for a maximum number of trains that might be in the block, only a broken wire or true short being sufficient to drop relay SCR. The current through the right-hand coil of DCR is decreased when check current of that block is drawn by one or more trains, because that coil of relay DCR is now in parallel with the trains' check circuits. The current through the left-hand coil of DCR is increased, being the sum current of the check currents drawn by trains in that block plus the current passing through the right-hand coil of DCR. Therefore a train having its control circuit closed draws a check current which opens relay DCR as relay TR of the same block drops. Relay DCR is arranged to open before relay TR has had time to drop. Therefore, because relays DCR and SCR are energized and open when TR drops, the control line is not grounded. Line 56 connecting trolleys 24 between coupled cars enables the train's check circuit completed on the lead car to take check current from each control block engaged by a trolley 24 of the train. Relays DCR are thereby opened in each control block engaged by a connected trolley 24. It is desired that each track block be cleared before the train stops drawing check current therefrom; accordingly trolleys or collector shoes 24 can be placed endward of the wheel contact points of each car or of the end cars; or, where only one trolley per car is provided, the track circuit blocks are preferably displaced relative to the control blocks as shown and explained, so that a car unshorts a track block before it stops drawing check current from the control block associated therewith or for the reverse direction of travel the car closes the check circuit of a particular block before shorting its rails. Train 20-21 which is drawing check current from block B and has shorted block C' with its forward wheels and axles without drawing check current from block C does not close the control-line grounding circuit, because relay DCR block B' has opened the grounding circuit of block C'; but when the trolley of car 21 passes into block C, unit 22, not drawing check current for a time period after uncoupling, allows relay DCR of the block which unit 22 shorts to drop. If a train does not ground a check current (indicating that the control or check circuit is not completed on the train) and with the adjacent block to the left unoccupied all other traffic approaching the shorted block will be halted by the grounding of the control line within the zone of control. A train which fails to receive a check current through its check circuit will be halted by its relay CR dropping. When a unit is uncoupled from a train at speed it is then only necessary to open the check circuit on the unit to slow the unit and halt approaching traffic without effecting the speed of the

train from which the unit uncoupled, since the train is then receding from the unit and rectifiers 26 prevent control between receding vehicles as will be explained.

Two-Way Signaling

5 Control to either a faster or slower forward vehicle, i.e. two-way control signaling, is provided by bypassing rectifiers 26 through front contacts on relays TCR whenever an A.C. current of frequency F1 selectively supplied from a train is received by one of these relays. A coil of each relay TCR is connected to the D.C. ends of full-wave bridge rectifier 70. One A.C. end of 70 is grounded, rail 11 being a common for all grounds, and the other A.C. end is connected in series with a series-parallel-tuned frequency-selective circuit 71 to line 28. Circuit 71 passes frequency F1 sent from a train moving from left to right to close relays TCR ahead of the train and establish a two-way control circuit. Each block section of line 14 having segments 16 connected through rectifiers 26 has a line 72 connecting segments 16 at opposite ends of that block. Line 72 is connected from the output side of rectifier 26 at the right-hand end segment of block B in series with A.C. choke 73 and front contacts on relay TCR block B to beyond the last rectifier 26 at the left-hand end of block B. Chokes 32 and 73 prevent A.C. check current from passing from one block to another. Choke 73 and front contacts of relay TCR are bypassed by wide-tuned band-pass circuit 74 designed to block the control-line-check and intertrain-control currents and to pass three different frequencies including F1 which circuit 71 passes to close relays TCR in chain succession in the portion of the zone of control to the right of the first block receiving F1 from a train. Thus lines 28 and 72 form a current loop in each block when contacts of TCR of that block are closed whereby control current from any segment in the block can traverse the loop to any or all segments within the block and whereby all rectifiers 26 which were bridging control blocks together ahead of but not behind the train traveling from left to right are bypassed for two-way conduction.

40 For operation in the reverse direction the trains send frequency F2 which is not passed by filters 71 but which is passed by circuits 74 to close relays TCR in succession by energizing another coil thereon. This coil is connected to terminals of full-wave bridge rectifier 76. One A.C. end of 76 is grounded, the other connected in series with frequency F2 selective pass circuit 78 to line 26 in the next block to the right of TCR. Thus relays TCR are closed in either direction from a train to the end of the zone of control depending on frequency F1 or F2 being sent from a train, whereby a unit can be uncoupled and slowed from a train at speed with the control current blocked by rectifiers 26 between the train and unit to prevent the unit from slowing the train even while the train sends the signal F1 or F2 bypassing rectifiers 26 in the zone of control ahead of the train to limit the speed of a forward unit to couple it.

45 Alternators F1' and F2' on the car FIGURE 2 supply respectively frequencies F1 and F2 either of which can be manually connected to line 14. Alternator F1' or F2' is connected to trolley 24 by a circuit following the check circuit from trolley 24 through back contacts of relay COR, and from there in series normally open contacts 79 of operator's switch 80, F1-F2 selector switch 81 (hand operated) to alternator F1' or F2' respectively in series with frequency F1 and F2 limited pass filters 82 and 83 to ground. By connecting F1' or F2' to line 14 through contacts on COR the operator on an uncoupled unit cannot slow the forward train by establishing two-way control therewith during the time delay period in which relay COR is open.

Intertrain Control Circuit on Vehicles

50 Referring to the car control circuits FIGURE 2, the intertrain control circuit on this vehicle, arranged for

operation in either direction on track 10 of FIGURE 1, is connected from collector 24 engaging control line 14 to rails 11 and 12 in series with segment 57 on the traction-power reverse switch REV to contacts 86 on coupling switch CS or CS' whichever is at the front of the vehicle as determined by the position of REV, line 88, A.C. choke coil 53, resistor 90, resistor 59, current limiting series field 92 and armature of D.C. dynamo DYN in series to wheels and rails. Coupling switches SC and SC' located on opposite ends of each car are of the spring return push button type arranged to be pressed open between coupled cars and closed at the ends of the train. Electrical connections to be made on either the front or rear car of a train are connected through the coupling switch at respectively the front or rear through contacts on reverse switch REV the position of which determines which end of the train is front. This main control circuit is therefore closed on the front car only of units or trains of one or more of these cars.

Dynamo DYN is preferably driven at a speed proportional to the r.p.m. of the car wheels 94 through positive drive 95 and is excited from vehicle control-power battery 96 or other dependable supply. As an alternative the dynamo could be driven at constant speed with field excitation dependent on the speed of the car; or the control circuits can be adapted for an A.C. dynamo, as shown in FIGURES 5, 9, 10, 11 and 12, or replaced with a rheostatic voltage divider, as shown in FIGURE 13. In any case the voltage output of the units vary with speed, and the output voltage is the same for all vehicles at the same speed with zero control current except when the voltage is adjusted to balance or reach zero control current at a safe speed difference. Current direction through the car's control circuit determines whether the car should be stopped or accelerated. When the dynamo is generating, the control current for that vehicle is called a stopping current, and when motoring, the control current is called an accelerating current. The potential fed by DYN to the control line is selected to be positive when the car is traveling from left to right and negative when traveling from right to left on track 10. Whenever a sufficient control current flows from car 22 to control line 14 and down through a car of unit 20-21 with cars moving from left to right car 22 is to be slowed and/or unit 20-21 accelerated until the voltage difference between units is balanced to zero at a safe or zero speed difference. An adjustable resistance 98 bypassed by normally closed contacts 99 of operator's switch 80 is in series with the main field 101 of dynamo DYN to enable the operator by opening contacts 99 to insert resistance 98 reducing the field and voltage of DYN so that the voltage difference between his train and the forward unit is balanced out at a speed difference at which his train approaches the unit for safe coupling. This balancing speed difference is adjustable by varying resistance 98 as desired.

The current limiting series field 92 opposes the main field when dynamo DYN is generating, i.e. passing a current in the direction of its generated current, thereby reducing the output voltage; and field 92 aids the main field when the dynamo is motoring, thereby increasing the back electromotive force generated. By providing series fields 92 the intertrain control current is reduced by both the generating and motoring dynamos. This is the preferred means to limit the maximum control current and reduce the operating voltage range required of the intertrain control circuit relays.

When the direction of car operation is reversed over the same track both the polarity of DYN and connection of car controls to the intertrain control circuit are reversed, so that trains traveling in opposite directions toward each other will be stopped and so that the same trackway control circuits can be used for both directions of traffic.

The polarity of DYN is reversed by reversal of rotation of the car's wheels. To provide for a car being turned around, the main field of DYN is connected through re-

verse switch 102 across the positive of battery 96 and its negative ground return. Line 103 connects the positive of battery 96 to reverse switch 102. Reverse switch 102 is actuated by any suitable actuator such as 104 which is pivoted for movement in a transverse plane through the car at the center of the underside of a truck whereby trackway actuators 105 located on a certain side of the track are arranged to vertically move actuator 104 and throw reverse switch 102 if a car is turned around. Actuator lever 104 is latched in position by usual means until an actuator 105 engages the low end of this lever. By this arrangement whenever a car is either operated in reverse or turned around the polarity of DYN is reversed.

Automatic Controls

15 The car control portion of the intertrain control circuit is connected across resistor 59 and arranged to be reversed by reverse switch 60 operated by either movement of reverse switch REV or actuator bar 109. Switch 60 comprises a circular drum shown developed flat revolvably supported to reverse the controls each time it is turned a particular even fraction of a revolution. The drum has notches in which a spring engaged rider 110 holds the drum in position to prevent incidental turning as the car moves. Magnetic clutch 112 couples REV to reverse switch 60. Clutch 112 is engaged by the control current which throws REV in the usual manner so that whenever REV is thrown switch 60 is thrown. Switch 60 is connected so as to be thrown by and move actuator bar 109 20 pivotally secured at its middle in a horizontal plane to the bottom of a truck on the center line of the car so as to be turned by trackway actuator 105. Since switch 60 is coupled by clutch and turned by REV only while the vehicle is stationary, switch 60 is turned by bar 109 without ever turning REV. By this actuating arrangement switch 60 is reversed whenever either the car is reversed or turned around and operated over the same track past an actuator 105.

25 Operator switches determine the desired conditions of speed control namely: "controlled," to be controlled (accelerated or slowed) to substantially zero control current, which the operator can select by holding down switch 116 against spring pressure; "controlling," to not be controlled unless the control circuit requires stopping, selected by the operator holding down switch 80 against spring pressure; and "neutral," to be retarded to zero control current (no switch for the operator) selected if neither or both "controlled" and "controlling" conditions are selected by the operator.

30 Automatic accelerating relay AR, stopping relay SR, and overcurrent stopping relay OSR are separately connected across segments 118 and 119 of reverse switch 60 in series with resistor 120 across resistor 59. The circuit for accelerating relay AR comprises in series from segment 119, line 122, rectifier 124 arranged to pass an accelerating current, normally open contacts 126 on "controlled" switch 116, coil of automatic accelerating relay AR, front contacts 127 on clear track relay CTR (optional), line 128, back contacts of relay OTR in parallel with normally closed contacts 129 of "controlling" type such as those in general use. Front contacts 141 of relay CTR are connected across the back contacts of relays SR and OSR to enable a vehicle to accelerate when the track ahead is clear even though a stopping current is received from a rearward vehicle on the same section of the control line. Front contacts 127 prevent automatic acceleration except when the track ahead is clear. Contacts 127 can be omitted from relay CTR. Relay CTR is optional, since it takes care of special situations which can be avoided and because where line 14 is divided into segments shorter than the space between collectors 24 on the closest spaced trains relays CTR are not needed. Contacts 141 do not interfere with operation of this system where trackway control signaling for energizing relay CTR is not provided.

Stopping Delay

The distance-of-travel controlled rheostat 139 is driven through magnetic clutch 136 from reverse-shift-and-speed-reduction unit 142 from car wheels 94. Shift-and-reduction unit 142 is arranged to drive the rheostat from full to lowest resistance in both directions of vehicle movement by actuating a reverse lever 146 on unit 142 from reverse switch REV by means such as arm 147 extending from REV and linked to lever 146. Spring 148 returns rheostat 139 to full resistance position when clutch 136 is disengaged. Relay OTR controls the engagement of clutch 136. Relay OTR is arranged to be closed only when the intertrain control circuit is first closed and a high value of intertrain control current passes therethrough as results from a train at speed coming into intercontrol with a standing or slow moving car or train. The resulting stopping current on the approaching train is closed through relay OTR and passed by rectifier 132. This stopping current holds relay OTR closed until a very low value of stopping current is reached. This current also closes clutch 136 which turns rheostat 139 reducing the resistance in series with relay OSR as the train progresses. If the train operator holds down "controlling" switch 80 with OTR lifted he opens the circuit to relay SR at contact 129, and as long as the stopping current is not too high relay OSR is not lifted and the train can proceed indicating that the car ahead is accelerating sufficiently or the speed difference between the train and car is safe relative to their distance apart. For the operator's information ammeter AM is connected across resistance 59 to show the intertrain control current whereby the operator can "see" the car ahead accelerate. Rheostat 139 is so proportioned and driven as to convert the required safe reduction of maximum control current with distance to the substantially constant current value at which relay OSR operates. If the initial control current was not too high as to lift relay OSR the train can proceed as long as relay OSR or SR is not lifted. Relay OSR is only energized when it is necessary to stop or slow the train, as when the car ahead does not start or accelerate sufficiently relative to the speed of the train. It should be seen that a fast train will allow less time for a car ahead to start and accelerate than a slow train allows, and a train can progress until stopping is needed with a safety factor varied only by variation of the zone of control. The resistance of rheostat 139 reaches its low value before the limit of its travel is reached. Approaching this limit of travel with the control current through relay OSR at about its pull-in value relay OTR drops before clutch 136 disengages. The dropping of OTR opens clutch 136, and spring 148 returns rheostat 139 to full resistance position. Relay SR is now connected through back contacts of relay OTR.

The pull-in circuit of relay OTR is opened to prevent relay OTR from picking up and initiating a delay of stopping when a strong stopping current is received when, for instance, a train is approaching a car at coupling speed (practically zero control current) and the control zone suddenly bridges to a standing car ahead. Such a situation would lift relay OTR allowing the train to run

at unsafe speed into the car it is following were it not for relay PCR which closes the circuit of the pull-in coil of relay OTR only while the track ahead is clear and for a short time thereafter.

- 5 The coil of relay PCR is energized through a circuit which checks that there is no other train (open control circuit) in the zone of control before energizing relay PCR. While relay PCR can be energized by the clear aspect circuit SCS of a usual automatic train control or 10 cab-signal system which could be provided with my system for trains not having the intertrain control (the track circuits and relays TR being utilized therein), it is preferred to provide a simple and fool-proof arrangement for detecting a clear zone of control which can be used where automatic train control or cab signals are not provided and 15 where the rails are not insulated apart.

Line 150, FIGURE 1, is supplied with a frequency F3 by alternator F3' connected from line 150 to ground. The right-hand end of each control block is connected 20 from the output side of the rectifier 26 between the block and the block to the right in series with front contacts of relays BR and BR1 between these blocks in series, resistance 152, frequency F3 limited pass filter 154, to line 150.

- 25 On each train, FIGURE 2, frequency F3 is received by a circuit comprising in series trolley 24, segment 57 of reverse switch REV, contacts 86 on the coupling switch at the front of the train, line 88, line 156, full-wave rectifier 158 across the D.C. terminals of which is connected the coil of relay PCR, frequency F3 only pass filter 160, ammeter AM2 (optional) to ground. The frequencies F1, F2, and F3 are sufficiently close and arranged to be passed by band pass filter 74 from block to block along the control circuit within the zone of 30 control.

35 By this arrangement frequency F3 put on the control line 14 at the right-hand end of the control zone is received by all trains equipped with intertrain control throughout the control zone. Resistance 152 is high relative to the impedance of the circuit for F3 on each train and the remainder of the circuit supplying F3, whereby 40 relay PCR is arranged to close with full voltage of F3 on line 14 and hold when its energizing circuit is the only circuit drawing F3 within the zone of control and drop when the voltage is reduced (can be reduced to nearly 45 half) by the presence of another train drawing F3 current within the zone of control.

- 50 When a train at speed comes into intercontrol with a standing or slower moving train ahead with relay PCR lifted holding closed the circuit of the pull-in coil of relay OTR, relay OTR is allowed time to pick up before relay PCR drops. Then relay OTR is prevented from picking up again until relay PCR has lifted and OTR receives a 55 heavy stopping current.

55 A unit uncoupled just before a train comes into intercontrol with a car ahead to couple it at speed would prevent relay OTR from lifting, since relay PCR dropped when its current is reduced by the uncoupled unit drawing F3 current. The operator of such a unit should wait 60 for intercontrol with the car ahead before uncoupling, so that the train will not needlessly be slowed. A trackway marker could tell him where intercontrol would be established on approach to a station from which the vehicle ahead is to be accelerated. With the clear aspect 65 signal of a trackway control signal closing contacts 141 this situation is not encountered, since the presence of the uncoupled unit at the rear would not change the clear aspect for the train.

- 70 If it is desired to prevent automatic acceleration except when the track ahead is clear contacts 127 are provided to close the circuit of relay AR only while a clear track signal is received by relay CTR. Manual acceleration subject to automatic stopping then enables a following car to couple a train.

75 If it is desired to allow automatic acceleration when

the track ahead is occupied the following arrangement prevents a vehicle from being accelerated by a rearward vehicle into a forward vehicle at an unsafe speed. Across resistor 90 is connected normally closed contacts 162 of "controlled" switch 116. Across resistor 120 is connected normally open contacts 164 of "controlled" switch 116. Resistor 90 is inserted in series with the main control circuit (bypass opened) when "controlled" switch 116 is pressed down thereby reducing any control current to encourage any accelerating current to take a path through any train that might be within the control zone that is not ready to be automatically accelerated to reduce the speed to which the unit wherein switch 116 is closed can be automatically accelerated when a forward train or car within the control zone is not accelerated. Resistor 120 is bypassed when switch 116 is pressed down to enable a lessened total control current to supply the same stopping current to the stopping relays SR or OSR as it would with switch 116 open. By this arrangement plus the current limiting series field 92 described, the vehicle cannot be automatically accelerated very much when there is one or more trains which cannot be accelerated in the zone of control even when a fast train enters. Further, a train entering a zone of control having two stopped trains will feed control current to both causing its stopping current to be extra large, more readily stopping the entering train. Also the value of the control current read on ammeter AM can tell the entering train's operator, taking into account his speed, whether there is one or more units ahead in the control zone, and the operator of a unit beginning automatic acceleration can read if there is a standing unit ahead by a very fast reduction of his accelerating current and its reversal of direction at low speed to a stopping current gradually stopping the unit as the train behind slows to a stop. With this arrangement (contacts 127 of relay CTR being omitted or jumpered) and with switches 116 and 80 closed the unit can be automatically accelerated by a forward train to couple it. 90, 120, and 92 are made as large as needed.

Uncoupling

The operator's uncoupling switch 170 connects battery 96 to uncoupling control valve 172 through a check circuit which will not close if there is any control voltage supplied to line 14 by any following traffic or by any forward traffic moving toward the train within the zone of control. Switch 170 when closed by an operator against spring pressure connects the positive of battery 96 to line a connected through train line trunk T to line a', through segment 174 on reverse switch REV to contacts 176 on coupling switch CS or CS' whichever is at the rear of the car as determined by REV and through the coupling switch closed on the rear of the train to line 178, front contacts 179 of relay 180, back contacts of relay 182, line b connected through train line trunk T to b', contacts 184 of switch 170 now closed by the operator on the car to be uncoupled, contacts 186 closed when the end passage between the forward car is locked closed and the car made ready for uncoupling, coil of solenoid valve 172 to ground all in series. The coil of relay 180 is connected from line 178 to ground, so as to be energized on the rear car of a train when an operator closes a switch 170 on the train. Line 56 connecting trolleys 24 is opened on the last car of the train (or optionally on any car behind the front car) through back contacts of relay 180 ahead of the engaged collector 24. The coil of relay 182 is connected from collector 24 to ground in series with front contacts 188 of relay 180. Front contacts 179 close after front contacts 188 and after relay 182 has had time to open, so that if there is traffic which sends an accelerating current this opens relay 182 preventing the completion of the uncoupling circuit as long as relay 182 is energized. If the fore part of the train were on the same length of control line

14 this would prevent the unit from uncoupling until a rectifier 26 passed between the cars separated by an energized relay 180. Where trolley or third-rail shoes are provided at both ends of the car the uncoupling switch 5 opens the circuit of the forward trolley to utilize the sectionalization of the control line to prevent control between the train and the uncoupled unit, one arrangement whereby the coupling switch opens the forward trolley being shown and described with FIGURE 16. A car 10 having a complete control station at each end would have two sets of uncoupling circuits and operator switches.

When the circuit to valve 172 is closed the unit is uncoupled. When the coupling pin is fully lifted it closes contacts 194 connecting a circuit from positive of battery 96, line 193, line 196, contacts 194, pull-in coil of stick relay 198, to ground. An uncoupled-car stopping circuit is closed from the positive of battery 96, line 193, line 199, front contacts of relay 200, front contacts and hold coil of relay 198, coil of uncoupling stopping relay 200, USR, to ground. The coil of relay 200 is connected across generator 202. Generator 202 is driven according to car speed from drive 95 so as to energize relay 200 and hold the stopping circuit closed to energize relay USR down to a low car speed whenever stick relay 198 closes, 25 indicating that the car is uncoupled from the forward car of a train. Operator controlled valves or check valves in the ends of the air hose lines shut off the air between uncoupled cars.

Master Controller Drive

30 Cam shaft or drum controller 208 is driven by pilot motor PM through worm 210 on the motor's shaft engaging worm gear 211 secured on shaft 212, spur gear 213 secured on shaft 212 engaging spur gear 214 secured on the shaft of controller 208 providing speed reduction from motor PM to controller 208 with shaft 212 driven at an intermediate speed. The cam of a controller positioning cam switch 216 is secured on shaft 212, and the cam of a controller off-position switch 217 and controller 40 full-speed position switch 218 are secured on the controller's shaft. Pilot motor PM is preferably driven from battery 96 insuring that the pilot motor can return to off position with the power off. Motor PM could have a permanent-magnet field or else as shown have its field coils 220 connected across battery 96 in series with front contacts 221 on pilot-motor operating relay 222, contacts 221 having in parallel therewith normally open contacts 223 on "control" switch KS. The pilot motor's armature is connected to drive drum 208 to start and accelerate the vehicle by a circuit from the positive of 45 battery 96, contacts 223 of switch KS or front contacts 221 of relay 222 in parallel, front contacts 225 on pilot-motor reversing relay 226 which controls the notching up and down of contactor 208, armature of the pilot motor, front contacts 227 of relay 226 to the ground side of 50 battery 96. The pilot motor's armature is connected for deceleration and stopping by the circuit from the positive of battery 96, front contacts 229 of relay 222, back contacts 230 of relay 226, armature of pilot motor PM, back contacts 231 of relay 226, back contacts of relay 60 HR, to the ground side of battery 96. The coil of pilot motor operating relay 222 is connected across battery 96 in series with contacts of off-position cam switch 217 opened only in off position of controller 208. Step-position cam switch 216 opens its contacts on each controller step or contact position of drum 208 and is connected in parallel across the back contacts of relay HR. Full-speed switch 218 on controller 208 opens at full speed position dropping relay 226.

Control Power Limited To Head End

70 So that only the car at the head end of a train may be in control, a segment 232 on the operator's reverse switch REV connects line 234 from the positive of battery 96 to head end control supply line 236 through contacts 238 on

coupling switch CS or CS' whichever is at the front as determined by REV. Contacts 238 are open between coupled cars and closed only when there is no car coupled to the end on which coupling switch CS or CS' is located. Thus line 236 is connected to battery 96 only on the leading car. Line 240 connects power from line 236 through front contacts of relay BR to drum 208 and to the coil of relay TLR which when energized closes the circuits from drum 208 to respective train lines of trunk T. Relays TLR isolate the train lines from the drums 208 which are not on the leading car, so that as soon as cars couple only the leading car will be in control, and so that train lines cannot feed power to drum 208. The removal of power from train line T1 (by the dropping of relay BR) applies the brakes. If the leading car is out of service the coupling switch contacts 238 which are at the front of another car can be jumpered. If it is desired to back up a train the reverse switch segment 232 can be jumpered to the coupling switch contacts 238 which are at the rear. When such jumpers are used a manually-closed spring-opened switch would be in series with each jumper.

Accelerating, Holding, and Braking Circuits

The accelerating circuit comprises in series from the control-power head-end-selecting line 236, line 242, front contacts on holding relay HR, normally open contacts 244 on spring opened operator's control switch KS in parallel with front contacts of accelerating relay AR and normally open contacts 246 of spring opened automatic-control switch 116 in series, full speed switch 218 opened at full speed position of drum 208, and coil of relay 226 to ground. The holding circuit comprises in series from line 236, front contacts of check relay CR, operator's brake applying switch BS, back contacts of relay USR, holding switch contacts 243 engaged in through full-closed position of operator's control switch KS, back contacts of relays OSR and SR, and coil of holding relay HR to ground.

Though brakes are applied when the controller 208 reaches off position by opening power to train line T1, it is preferred that brakes be applied immediately when needed by either the operator or automatic control without waiting for the pilot motor to return drum 208 to off position. Accordingly brakes are applied by opening the circuit to the coil of relay BR connected in parallel across a portion of the holding circuit. The coils of relays BR and HR could be in series, but it is preferred not to apply the brakes when a control circuit stopping current is received if reduction of power to the motors will correct the speed difference. Therefore the coil of relay BR is connected to the holding circuit ahead of contacts 248 of KS in series with back contacts of relays SR' and OSR' whose coils are connected across the coils of relays SR and OSR respectively so as to operate at a heavier control current than relays SR and OSR respectively. When only a slight speed correction is needed relay SR or OSR operate and relay SR' and OSR' remain closed. When brakes must be applied to correct the speed difference relay SR' or OSR' also opens. It should be noted that whenever relay BR drops relay HR drops or has dropped to return the pilot motor to off position. The opening of the holding circuit returns drum 208 to off position.

Interruption of Normal Controls After Uncoupling

Upon uncoupling a unit of one or more cars from a train the check circuit on the uncoupled unit is arranged to be opened for an interval at back contacts of relay COR. Relay COR could be energized by connecting its coil in series or parallel with the coil of relay USR, or as preferred and shown the coil of relay COR is energized for a time interval, effective even when the car is uncoupled when standing still, by time delay relay TDR. The coil of relay TDR is connected from line 236 to

ground so as to be energized when the coupling switch at the front of the car closes as the unit is uncoupled from the train. The coil of relay COR is connected from line 236 to ground in series with back contacts on relay TDR. 5 During the delay period relay COR holds open the check circuit on the uncoupled unit dropping relay CR energizing warning light 250 and buzzer 252 connected from line 236 through back contacts of relay CR to ground and opening the holding circuits to relays BR and HR respectively applying brakes and returning the pilot motor. 10 The last car of the forward train drawing check current having passed beyond the block occupied by the uncoupled unit, the control line 14 is grounded in the block occupied by the uncoupled unit through line 52, choke 66, back contacts of relays TR and DCR of that block to rail 11, grounding through rectifiers 26 all block sections of line 14 bridged together relative to traffic from either direction approaching the block occupied by the uncoupled unit. Back contacts on relay TDR open the current supply to 15 the coil of relay COR after the delay period dropping relay COR. Relay USR being energized through the uncoupling circuit holds open the circuits to the coils of relays BR and HR after the delay period until the uncoupled unit reaches a low speed at which relay 200 drops dropping relay USR releasing the brakes and returning 20 accelerating control to the operator.

Manual Switch Arrangement

"Controlled" switch 116, as shown in FIGURE 3 has 30 secured thereto a side extension 254 arranged to close switch KS halfway when switch 116 is closed full. When the operator presses KS down about halfway contacts 248 close the holding and brake releasing circuits, and contacts 223 close. When he presses KS all the way down 35 the car is accelerated with holding contacts 248 and accelerating contacts 244 of KS closed. Thus contacts 223 and 248 are closed by either switch KS or 116, and the operator at the head end of the train by resting his hand on switch 116 holds KS closed halfway when waiting for 40 and during automatic control.

Operation of the Controller

When an accelerating current is received from a train approaching from the rear (the polarity of a train approaching from the front provides a stopping current) 45 relay AR closes. Then with switches 116 and BS closed, relay CR energized, and pilot motor PM in off position of the control, relay 226 is energized driving the pilot motor to turn drum 208 to accelerate the unit. When 50 the unit accelerates to the speed of the following train the accelerating current drops to zero dropping relay AR, which drops relay 226 (unless the operator chooses to accelerate his unit by closing switch KS) causing the pilot motor to return to the last notch position of drum 208 55 whereat switch 216 opens stopping the pilot motor and holding the car controls on this running notch. If it is undesired that all notches be selected by the operator because of the resistance loss when running on these notches the cam of notch position cam switch 254 is 60 secured on the shaft of drum 208 to open only at manual running positions and connected in series with contacts 256 on the operator's control switch KS across the contacts of notch cam switch 216, contacts 256 being arranged to close after considerably past halfway but before KS is fully closed. The car will continue to accelerate, since it takes time for the traction motors to reach 65 full speed for a given voltage applied. When the unit exceeds the speed of the train trying to couple it a stopping current is received lifting relay SR which opens the holding circuit dropping relay HR closing the circuit for the pilot motor to return. As the pilot motor returns and the unit starts to slow down the stopping current dies out, relay SR drops, relay HR is energized, and the pilot motor stops drum 208 on the highest notch remaining 70 closed. By similar operation the pilot motors on both 75

the unit and train are controlled to closely maintain balancing speed (zero control current) at which the train can follow or couple the unit ahead as the train's operator desires.

Variations

In the variations to be considered hereinafter like parts have the same reference numerals. Many details shown in FIGURES 1-3 are not shown in the variations, but it should be evident that these parts and features can be added and variations of parts can replace corresponding parts in various variations. Pass filters are those which attenuate all frequencies which may be encountered except those which are specified to be passed thereby.

Wherever it is impractical to insulate apart the track rails 11 and 12 as on street railways or undesirable to install or use existing track circuit blocks for this control system the control blocks are confined to the control conductor or conductors. One such arrangement is shown in FIGURE 4 together with further variation over FIGURES 1 and 2 in that the control circuit is opened on a unit for an interval after uncoupling from a train with conditions safe, thus dispensing with the need for dividing control line 14 into segments 16 to interrupt the control between the train and uncoupled car.

Referring to FIGURE 4, control line 14 is divided into block lengths A2, B2, C2, etc. insulated apart by insulators 18. Each control block has a block circuit supply transformer 260 whose primary is connected across supply lines 262 and 263 and whose secondary is connected from ground to the left-hand end of line 14 in that block in series with filter 264 arranged to attenuate all currents except the block supply current. Each block has coils of control line block bridging relays BR2 and BR3 connected from the right-hand end of their block length of line 14 to ground, both in series with filter 266 passing only the current from the transformer 260 connected to the same block. Back contacts on relays BR2 and BR3 bridge the block from which they are energized to respectively the right and left-hand adjacent block. Relays BR2 and BR3 between adjacent blocks bridge across the control line insulator 18 therebetween in parallel and both in series with impedance coil 32 and rectifier 26. Relays BR2 and BR3 have front contacts which connect power from line 268 to the coils of respectively relays BR4 and BR5 arranged to bridge through back contacts the far end of the next block respectively to the right and left in parallel with the back contacts of the relays BR2 and BR3 which bridge these blocks. A circuit from trolley 24 to ground on each vehicle connects the coil of relay CR through filter 270, which passes current from transformer 260 only, to ground a sufficient amount of block circuit current to cause relays BR2 and BR3 to drop when a train enters their block, dropping relays BR4 and BR5 which were energized therethrough bridging a series of blocks into a zone of control.

If it is desired to provide two-directional control current, signal generator or alternator F1' engaged by "controlling" handle 80 is again connected from trolley 24 to ground in series with frequency selective circuit 82 to prevent grounding of other frequencies therethrough. This signal is arranged to energize relay TCR1 connected in series with filter 71 from the right-hand end of each block length of line 14 to ground for traffic movement from left to right where cars are accelerated to couple trains and is omitted where not desired as between blocks B2 and C2. Front contacts of relay TCR1 are connected across rectifier 26 at the exit end of the block to which that relay TCR1 is connected, whereby two-way control current can pass insulators 18 when relays TCR1 are energized by the train operator closing switch 80 to slow a unit ahead to couple it.

Along track 10a is shown train 20a-21a and train 22a which has uncoupled therefrom. The control circuit for each train from collector 24 to point J comprises

in series, segment 57 of traction power reverse switch REV, contacts 86 on the coupling switch CS or CS' whichever is at the front of the train according to the position of REV, line 88, back contacts 272 of control circuit opening relay COR', and A.C. choke coil 59. The automatic train controls for FIGURE 4 connected from point J to the rails can be considered the same as those shown in FIGURE 2 from point J to the rails and therefore are not repeated but represented as ACC2 in FIGURE 4.

In parallel across back contacts 272 of relay COR', rectifier 274, arranged to pass a stopping current, is connected in series with front contacts of relay COR' and contacts 276 and 277 on reverse switch 60. Relay COR' is energized by the circuit from the positive of battery 96, segment 232 on REV, contacts 238 on the front coupling switch CS or CS' as determined by the position of REV, line 236, back contacts of relay TDR, the coil of relay COR', and ground return to the opposite side of battery 96. The coil of relay TDR is connected from line 236 to ground.

On each train a check current is supplied by signal generator or alternator F4' connected from the control line side of impedance 59 to ground in series with F4 limited 25 pass filter 280 and back contacts 281 of relay COR' which open this check circuit during the time delay period of relay TDR commencing upon the uncoupling of the unit from the train. A control grounding relay CGR is energized from this check signal F4 of generator F4' through filter 280, back contacts of COR', line 88, contacts 86, segment 57, trolley 24, control line 14, line 282 in each block occupied by the train, F4 pass filter 283, full-wave rectifier 284 across the D.C. terminals of which the coil of relay CGR is connected, to ground return to alternator F4'.

When unit 22a uncoupled, contacts 86 on coupling switch CS at the head end of the unit closed, connecting the coil of relay COR' to battery 96, lifting relay COR', opening the control circuit relative to the faster moving 40 forward train, and closing the control circuit through rectifier 274 relative to a slower moving forward train. If relay 180, FIGURE 2, were now energized on the forward train the uncoupled unit would send a control current through rectifier 274 to the rear car of the forward train which would hold open relay 182 and so prevent a 45 second unit from being uncoupled from train 20a-21a until the train passes beyond the zone of control of the uncoupled unit or the uncoupled unit practically stops. Relay COR' when lifted during the delay period, also 50 opens the circuit of alternator F4', dropping relay CGR in the blocks occupied by the unit after the forward train has passed beyond these blocks.

A unit uncoupled from a train grounds the blocks behind preferably the forward block occupied by the unit 55 to the end of the zone of control with respect to the D.C. control circuit of following vehicles and grounds the A.C. block current of all blocks occupied during the delay period for a time longer than the delay period of relays TDR. When unit 22a moves into block B2 train 20a-21a having moved beyond block B2, block A2 will have a D.C. ground and block B2 will have a grounded 60 A.C. block circuit. The D.C. grounding circuit comprises from line 14 block A2, line 286, back contacts 287 and 288 on respectively relays CGR1 and CGR block 2, choke 66 block B2, resistance 290, all in series to rails and ground. Resistance 290 enables a signal to be received from an uncoupled unit occupying a grounded block, which will prevent the train 20a-21a from uncoupling a second unit before the first has slowed down 65 sufficiently. The coil of relay CGR1 block B2 is connected in parallel (or series) with the coils of relays BR2 and BR3 of block B2 so as to also drop when the check current drawn by relay CR of a train occupying block B2 drops relays BR2 and BR3 thereof. The A.C.

grounding circuit comprises in series from line 14, line 282, block circuit current limited pass filter 292, back contacts 293 on relay CGR1, coil and back contacts of time delay relay TGR, back contacts 294 on relay CGR, resistor 295 across which is connected a red signal lamp R, to ground. The grounding of the block current of block B2 keeps relay CGR1 from being reenergized after unit 22a passes to block C2 until time-delay relay TGR opens after delay relay TDR on the unit has had time to open, completing the check circuit of the unit, raising relay CGR, unshorting the block or blocks then occupied by the unit, the remaining shorted blocks being opened by the lifting of relays TGR arranged to open enough to allow relays CGR1 to open.

Cars of FIGURE 4 can be arranged to operate on the trackway of FIGURE 1, and the car shown in FIGURE 2 can have an alternator F4' added and be arranged to operate on the track of FIGURE 4.

Where it is desired to utilize the control line for traction currents or conversely a power distribution conductor as the control line the control circuit is varied and adapted to supply traction power to each section of the control line through an arrangement which prevents the control current from using feed or return conductors to go from block to block and by separating the traction from the control power on the cars. While A.C. traction power can be separated from D.C. control power, one arrangement being later described with FIGURE 10, it is preferred to provide an A.C. control circuit such as shown in FIGURES 5, 9, or 12 when A.C. or D.C. traction current is to be supplied on the same contact conductor with the control voltage. The A.C. control current is of a different frequency from the A.C. traction current so as to be separable therefrom.

Referring to FIGURE 5, along track 10b is run trolley wire 14a to provide electric motive power, speed control signaling, and a control synchronizing frequency for self-propelled rail units such as cars 20b and 22b represented by their wheels and axles on track 10b.

With rails 11b and 12b of track 10b insulated apart line 14a need not be divided by insulators into block lengths. Track 10b is divided by insulators 36 into double-rail track circuit blocks represented by blocks A3, B3, and C3. The track blocks are sufficient to limit the extent of the zone of control where the track is well ballasted, drainage is good, and the control voltage is kept low. Leakage past rail insulators could only extend the zone of control.

Each block can be considered similar to block B3 wherein the secondary 298 of track-circuit transformer 299 is connected across the rails at the left-hand end and track circuit relay BTR is connected across the rails at the right-hand end, all as usually provided in a track circuit. Each relay BTR closes through back contacts an electrical bypass or bridge circuit from the block across which relay BTR is connected to the adjoining block at the right across insulator 36 in rail 12b. This bypass includes back contacts 300 of relay BTR in series with a synchronous-rectifier unit SRU wherein rectifier 26a is arranged to pass return control current of a particular phase sequence and block current 180° out of phase therewith. Back contacts 301 of relay BR6 are connected across back contacts 300 of relay BTR. Relay BR6 is energized through front contacts on relay BTR one block to the right; and, if more blocks are desired to be bridged, relay BR6 can be energized through front contacts of relays BTR of a series of blocks to the right as shown for relay BR FIGURE 1. Relay BR6 block B3 is energized through the circuit comprising from supply line 302, line 303, front contacts on relay BTR block B3, coil of relay BR6, to line 304. Lines 302 and 304 also supply the primary of transformer 299 connected thereacross.

Synchronous rectifier SRU comprises a two segment commutator across which rectifier 26a is connected, secured, and rotated by synchronous motor SM at a speed

whereby rectifier 26a is reversely connected to brushes d and d' engaging the commutator 180° apart so as to cross segments every half cycle of the control circuit voltage as the control voltage passes through zero and half phase in phase therewith. These synchronous rectifiers permit A.C. control current to pass between approaching trains and completely block control current between receding trains. Synchronous motor SM is selected to be a two-pole motor and is connected across coil 306 of transformer 299 which is energized from the same source that supplies the synchronizing current to the trains. A positive drive speed increaser 307 connects motor SM to rectifier unit SRU for receiving the rectifier every half cycle in step with the control circuit voltage.

15 A check circuit optionally provided for checking that blocks are bridged comprises in series as shown between blocks A3 and B3, secondary 308 of transformer 299 block B3, back contacts 309 and 310 of respectively relays BTR block A3 and BR6 block B3 in parallel, signal lamp 20 W3, rail 12b block A3, bridging contacts 309 and 301 respectively of the same relays BTR and BR6 in parallel, synchronous rectifier unit SRU, rail 12b of block B3 to the opposite side of coil 308. This circuit checks the complete bridge circuit including the bridging conductors, 25 their connections to the rails, and relay bridging contacts.

Two-way control signalling again can be provided by providing on the cars frequency F1 by means of generator F1' connected from pantograph 24'a to ground in series with F1 pass filter 82a and operator's switch contacts 79, and by providing relays TCR along the trackway. Front contacts of relay TCR block B3 are connected in parallel with rectifier unit SRU. Relay TCR block B3 is connected across D.C. terminals of bridge rectifier 70 whose A.C. terminals are connected from control line 14a to rail 11b block B3 in series with F1 pass filter 71a and current limiting resistor 311. The range of F1 need not be great, since trains will usually be close together before the fine speed adjustment feature of two-way control is desired.

40 Impedance bonding between adjacent blocks provides a path for the return propulsion and synchronizing currents. The impedance coils 312 and 313 are connected as usual across the rails of adjacent blocks, but the center taps of the coils of adjacent blocks are connected together through a parallel-resonant circuit comprising impedance coil 314 and condenser 315 in parallel across the center taps of coils 312 and 313 of the impedance bond between adjacent blocks. The resonant frequency of the coil and condenser is such as to attenuate the A.C. control signal frequency.

50 A.C. or D.C. traction power is supplied to line 14a across terminals e—e' connected in series with attenuator 316 tuned to block the frequency of the control current from contact conductor 14a to the center tap of impedance coil 313 block C3. The D.C. dynamo of the preceding examples is replaced on each rail unit by a shunt or separately excited A.C. generator or dynamo ACD driven by a synchronous motor SM1 through positive-drive speed increaser 307'a arranged to synchronize dynamos ACD in phase on all trains. Dynamo ACD has a frequency output a whole plural multiple of the frequency F_s of motor SM1; whereby, with a given field polarity, the A.C. dynamos on all the trains on the system are synchronized substantially in phase with each other for movement in a given direction along the track. 60 Motor SM1 is connected from the pantograph 24'a engaging line 14a to the wheels of each powered unit in series with a series-parallel tuned filter 318 arranged to pass the frequency of motor SM1 and attenuate the frequency of the dynamo ACD, traction power, etc. Where A.C. traction power is provided it can be used to drive the synchronous motors. Where a different frequency for motors SM1 is desired or where D.C. traction power is provided A.C. is also supplied across terminals e—e' to conductor 14a for the synchronous motors. The dy-

namo's frequency is selected, but not limited, to be three times that of its drive motor; which, for example, is operated on 60 cycles, providing 180 cycles dynamo frequency. The larger the number of times the control frequency is relative to its synchronizing motor's frequency the greater any phase difference between motors SM1 would be magnified between dynamos ACD. Therefore the frequency multiplication between motor SM1 and dynamo ACD is preferably low but yet high enough for satisfactory separation by filter circuits. Each dynamo ACD is separately excited by a D.C. exciter DCE driven from a traction motor or axle, whereby the effective electromotive force of dynamo ACD represents car speed. A speed difference between trains is represented by a current between trains resulting from a control voltage difference between dynamos ACD on the different trains.

Since dynamos ACD are synchronized in phase on all the cars, they can be coupled together between cars in parallel across the control conductor and the rails similarly as if D.C. dynamos were used. At each instant, except when the dynamos ACD go through zero voltage, their relative output voltage represents speed as with D.C. dynamos. A wattmeter or wattmetric relay WR is connected with its potential coil across the output of each dynamo and its current coil in series with the control circuit of the dynamo whereby relay WR determines, except in a particular situation to be discussed with FIGURE 11, whether the dynamo is operating as a generator or motor, i.e. whether the dynamo is delivering current or receiving current respectively. The circuit of dynamo ACD comprises in series from the current collector to the rails 180 cycle pass filter 320, synchronous rectifier unit SRU1 in parallel with back contacts of relay COR', current coil of wattmeter relay WR, current limiting field and armature of dynamo ACD, to ground. The primary of the main transformer for A.C. traction or the traction motors for D.C. traction are connected across terminals $f-f'$ from the pantograph to the rails in series with an attenuator 322 of the 180 cycle control current and F1, F2, etc. currents. Attenuator 322 comprises one or more parallel tuned circuits and with the aid of the 60 cycle pass 318 and any other filters needed substantially prevent 180 cycle power from being lost before and after transmission.

Wattmeter WR is the zero centering type and is connected so as to turn to the right or left to accelerate or stop the vehicle when the dynamo on the vehicle is motoring or generating respectively. The relay WR has a sliding contact arm 324 which connects power from line 236 to the coil of accelerating relay AR when arm 324 turns to the right and connects power to the coil of relay OSR through rheostatic resistance 326 and to the coil of relay SR and to the circuit of the coil of relay USR when arm 324 turns to the left. Additional relays OSR and SR can be added in series with resistance 326 to operate at different values of control current. The portion of resistance 326 in series is decreased as contact arm 324 swings to the left from center.

Exciter DCE reverses polarity when operation is reversed causing a 180° phase shift of the dynamo, so that two vehicles approaching each other from opposite directions one in reverse and the other in forward will both be stopped. If vehicles are turned around and operated over the same track the main field of dynamo ACD is connected through contacts of reverse switch 102 whereby trackway actuator 105 controlling switch 102 establishes the proper polarity whereby cars approaching from opposite directions are both stopped independent of whether reversed or turned around. Switch 102 could be inductively operated from means located along the rails or trolley wire or even could be manually operated.

Synchronous rectifier unit SRU1 is similar to synchronous unit SRU. The commutator of unit SRU1 is secured to rotate with dynamo ACD so as to reverse polar-

ity in step with each half-cycle reversal of dynamo ACD. Since the dynamo's frequency is selected to be three times that of motor SM1, with a two-pole dynamo and a two-segment rectifier unit both can be driven on the same shaft by a positive drive speed increaser from motor SM1.

As an alternative to using speed increasers, the synchronous rectifiers SRU and SRU1 could be replaced each with rectifier unit SRU2, FIGURE 6, which has a six-segment commutator 330 with motor SM or SM1 directly connected and rectifiers 26b connected and secured across opposite segments reversely from adjacent segments to reverse polarity every 6th of a revolution in step with the control frequency.

Where it is not desired to use or provide track circuits to limit the zone of control the combined control and power supply conductor 14a is divided into control circuit blocks with traction power fed to each block through means which prevents the passage of control current etc. from block to block therethrough.

A control line block arrangement for supplying D.C. traction current to adjacent block sections of a control conductor is shown in FIGURE 7 where D.C. current is supplied from line 334 through impedance coil 335 to the center tap of impedance coil 336 the ends of which are connected across adjacent block sections A4 and B4 of control line 14b. This impedance bond prevents passage of A.C. signal current from one block to another and to line 334 but permits D.C. passage from line 334 to either or both control blocks connected thereby. Block bridging relays BR7 and BR8 are connected from supply line 334 each in series with a series-parallel tuned circuit 338 arranged to pass the synchronizing frequency to motors SM1 on the cars to respectively the left-hand and right-hand block ends. A block bridging circuit is connected across adjacent block ends and has in series synchronous rectifier SRU3, arranged to pass first half cycles of control current from left to right and second half cycles from right to left from block to block and front contacts of relays BR7 and BR8 in parallel, whereby whenever a car takes synchronizing current for motor SM1 from a block the block relays BR7 and BR8 at opposite ends of the block wherefrom the vehicle takes power are energized and bridge that block to adjacent blocks. Since coil 336 would pass equal synchronizing current to each adjacent block, as when one or more trains draw current from adjacent blocks, coil 335 is provided to block this current so that relays BR7 and BR8 will be sure to close. Front contacts of relay TCR1 bypass rectifier unit SRU3 for two-way control signaling between trains. Relay TCR1 is energized by frequency F1 sent from a train and passed by series-parallel tuned filter 71.

A control line block arrangement for supplying A.C. or D.C. traction current to adjacent block sections of the control conductor is shown in FIGURE 8 where A.C. or A.C. and D.C. current is supplied through impedance bonds 340 to blocks A5, B5, and C5. Impedance bonds 340 each have three coils 341, 342, and 343 of the same number of turns on a core. The central coil 342 is connected from supply line 344 to an end of each of the other two coils arranged to counteract the flux of the central coil. The other ends of the outer coils are connected one to each adjacent block end of block sections of control line 14a. This impedance bond does not pass the A.C. signal current from one block to another, since current in series through both outer coils induces a sum flux in the core of the impedance. Bonds 340 permit A.C. or D.C. traction current to pass from supply line 344 to either or both blocks coupled to its outer coils, since the current in the center coil is equal to the sum of the branch currents in the outer coils and the flux of the center coil is neutralized by the outer coils. Block bridging relays BR9 and BR10 are provided at respectively the right and left-hand end of each block. The coil of relay BR9 is connected from line 14a in its block to ground in

series with F4 pass filter 348 which passes frequency F4 differing from the traction current and drawn by motors SM1 on the trains of FIGURE 5. Line 349 supplies F4 to line 14a in each block through a resistance 350 and F4 pass filter 351 in series. If F_s differs from the traction current F4 can equal F_s. The coil of relay BR10 block B5 is connected from line 14a block C5 to ground in series with F4 pass filter 352, and front contacts of relay BR9 block B5. Block A5 is bridged to block B5 through back contacts of relays BR9 and BR10 in parallel and of respectively blocks A5 and B5. Similarly block B5 is bridged to block C5 through back contacts of relays BR9 and BR10 of respectively blocks B5 and C5. Relays BR9 and BR10 drop when a train draws from the blocks feeding these relays current F4 separated respectively by filters 348 and 352 from the traction current. Frequency F4 differs from any A.C. traction current supplied so that it can be relatively shorted by the trains sufficient to drop relays BR9 and BR10. F4 current drawn by a train in a block increases the voltage drop across resistor 350 in that block sufficiently so that relays BR9 and BR10 controlled thereby are dropped. A check circuit is shown for the bridge between blocks A5 and B5 and comprises in series secondary of supply transformer 354, back block-bridging contacts of relays BR9 and BR10 of respectively blocks A5 and B5 in parallel, and signal lamp W4. Rectifier unit RU of any suitable type is added in series with the bridge path between blocks A5 and B5 where cars are uncoupled at speed and stopped.

Control-line, or more generally trackway, rectifiers or rectifier units are primarily utilized to block the speed control current between an uncoupled unit and the forward train and can be omitted beyond the zones of control extending forward from each and every block in which units are uncoupled and stopped. Acceleration away from another vehicle not separated by a trackway rectifier can be provided by allowing acceleration on a clear track signal.

The attenuators preferably do not have series condensers where they must pass traction currents. Also I avoid blocking a condenser with a rectifier except a synchronous rectifier.

With the aid of FIGURE 9 another arrangement for polarizing an A.C. intertrain control current and another arrangement for separating traction from control current will be described. Only the first half of each cycle of control current is selected to be transmitted by the trains 20c and 22c except when two-way control is desired when the full cycle is transmitted. On each train a synchronous commutator SC driven by motor SM3 passes alternate half cycles and blocks the other half cycles. The same half cycles are passed on all trains in either direction of operation through a circuit comprising from current collector 24c, line 356, D.C. or A.C. traction voltage bucking generator 358, brushes g—g' engaging commutator SC which has insulator inserts 360 about its otherwise conductive circumference so as to alternately connect and disconnect brushes g and g' on alternate half cycles, reverse switch 69 across which is reversibly connected rectifier 274 arranged to pass a stopping current, current coil of wattmeter relay WR, armature of dynamo ACD to the rails. Back contacts of relay COR' are again connected across rectifier 274 to be opened for the delay period of relay TDR FIGURE 4.

D.C. or A.C. traction voltage bucking generator 358 is driven by motor 364 connected in series with a control frequency attenuator 366 and optionally a variable resistor 368 from trolley 24c to ground whereby the generator develops a voltage approximately equal to the traction supply voltage at the car. For A.C. traction generator 358 and motor 364 are both synchronous machines with the field of generator 358 varied with line voltage preferably by connecting its field 370 or a portion thereof across a D.C. exciter 372 driven by A.C. series motor 374 connected from trolley 24c to ground in series with

control frequency attenuator 366 arranged so that voltage of generator 358 equals and varies with line voltage. For D.C. traction, motor 364, preferably a shunt motor, varies the speed of generator 358 with variation of line voltage so that generator 358 counterbalances the traction voltage in the control circuit preventing passage of traction current through the control circuit on the car.

Since only the first half of each cycle of the control current is used, the other half can be transmitted for other signaling purposes. Two-way control signaling is provided by bypassing brushes g—g' through normally open contacts 376 of switch 80 in parallel with a path including normally closed contacts 378 of switch 80, holding coil and front contacts of relay 380, and coil of relay 381, all in series across brushes g—g'. A second synchronous commutator SC2 closes contact between brushes h and h' during the second half of each cycle when brushes g—g' are electrically separated. Commutators SC and SC2 are positioned and secured on the shaft of synchronous motor SM3 which is connected from trolley 24c to ground in series with frequency F_s pass filter 318. A circuit is connected from the ground side of generator 358 to ground through normally closed contacts 382 of switch 80, brushes h—h' engaging commutator SC2, pull-in coil of relay 380, and back contacts of relay 381. When switch 80 on train 22c is closed by an operator, commutator SC is bypassed through contacts 376, and both half cycles of each cycle of the control current can pass from dynamo ACD of train 22c to trolley wire 14c. Trackway rectifier 26 can then pass half of each cycle irrespective of the phase sequence of the current, i.e. independent on whether the faster train is behind or ahead of another. A forward train 20c completes the polarized control circuit when slower moving relative to train 22c through brushes g—g'. Forward train 20c completes the two-way control circuit when the second half of control current cycles are received. If trains 20c and 22c were not separated by rectifier 26 the second half of the cycles of control current would be received by train 20c when the operator on train 22c closes switch 80 while train 22c is in motion above a minimum speed in either direction, switch 80 on train 20c being open. With one or more rectifiers 26 in the intertrain control circuit the second half of each cycle (being negative for a train moving from left to right) would not be passed by rectifier 26 unless train 22c travels slower than train 20c. Whereupon the second half of each cycle on train 20c being more negative than that of train 22c then enables train 22c to send a current past rectifier 26 to train 20c. The reception of the second half of control current cycles by train 20c energizes stick relay 380 which closes and holds two-way control closed through its front contacts. The closing circuit is preferably opened by relay 381 to prevent cyclic energy loss through the closing circuit.

These features illustrated in FIGURE 9 can replace the synchronous rectifiers SRU and SRU1 and various filters of FIGURE 5 permitting the use of stationary rectifiers 26 in place of synchronous rectifier units SRU along the trackway.

The operations of wattmeter WR and its limitations in the control circuit are illustrated by FIGURES 10 and 11 wherein train 22d is traveling to the right and train 20d FIGURE 10 is traveling to the left at about the same speed. During the first half of each cycle dynamo ACD of train 22d is positive and of train 20d negative at the control line side causing a strong stopping current to flow through both trains as indicated by arrows. Wattmeters WR on both trains read "stop" with both the current and voltage coils of the two wattmeters passing current in opposite directions as shown. If train 20d were slowed down relative to train 22d, at some slow speed of train 20d relative to 22d the current through the voltage coil of WR of train 20d would reverse as illustrated by FIGURE 11. When a dynamo

does not generate enough voltage to equal the IR drop of its armature (current from a dynamo on another train causing the high voltage drop) the current through the voltage coil of the wattmeter will be reversed as shown to indicate that the dynamo is operating as a motor when actually it is still a generator, since its back E.M.F. is negative down to zero speed. Thus a wattmeter is not always correct in determining when the dynamo ACD is generating or motoring. The current through the series coil is not reversed unless train 20d is operated in the reverse direction faster than train 22d, i.e. not until trains 20d' and 22d are diverging. Therefore the direction of the control current during a particular half of each cycle of the control current (or during a D.C. control current) provides a more completely reliable indication of whether a dynamo is generating or motoring than a wattmeter in the control circuit. Nevertheless a wattmeter can be safely used even when trains approach head on at a large speed difference, since the faster train will be slowed and at a lesser speed difference both trains will be slowed to stop.

Returning to FIGURE 9, the voltage coil of wattmetric relay WR instead of being connected as shown on train 22c, can be connected in series with a reversible synchronous rectifier SRU4 arranged to pass current from dynamo ACD on that train. Rectifier SRU4 is connected across contacts on reverse switch 60 so as to be reversed with the direction selected for train movement. Rectifier SRU4 blocks both half cycles of current to the voltage coil of wattmeter WR from any train that sends a control current which would turn relay WR to "accelerate" when the operator's reverse switch is in position to accelerate train 20c in the wrong direction. Rectifier SRU4 is reversed in synchronization with the intertrain control voltage by a positive-drive three-to-one speed increaser 307b connecting it from motor SM3 so that when synchronous commutator SC is bypassed for two-way control rectifier SRU4 remains effective by blocking each half cycle when accelerating current which would accelerate the train in the wrong direction is received.

FIGURE 12 combines the motor controls of FIGURE 2 with an A.C. intertrain control circuit wherein a synchronous commutator SC3 alternately connects similar pairs of reversed rectifiers into the control circuit on alternate half cycles whereby control current of either phase sequence is passed between trains and separated by the rectifiers on the trains to determine the direction of an approaching train, which direction represented by a particular phase sequence is checked through the reverse switch 60 before permitting automatic acceleration or stopping. The intertrain control circuit is again suited for connection over A.C. or D.C. traction lines except that D.C. traction is selected, which means that the attenuator 322 of FIGURE 5 for blocking the control currents from the traction circuit is simply a choke 390.

The intertrain control circuit on the car of FIGURE 12 comprises in series from pantograph 24a, pass filter 320a arranged to pass the A.C. control circuit frequency which is selected to be 120 cycles for this example, center brushes 392 engaging commutator SC3, brushes 393 and 394 each in parallel connecting a rectifier respectively 395 and 396 arranged to pass current from control line 14a in series with the coil of an accelerating relay respectively AR1 and AR2 each in parallel with a rectifier respectively 397 and 398 arranged to pass current to the control line in series with the coil of a stopping relay respectively SR1 and SR2, current coil of wattmetric relay WR2, and armature of A.C. dynamo ACD to ground. From the positive of battery 96 power is connected through front contacts of either relay AR1 or AR2 selective by segment 400 on reverse switch 60 to the coil of accelerating relay AR in series with operator's switch 116. From the positive of battery 96 power is connected through back contacts of either relay SR1 or SR2 selective by segment 402 on reverse switch 60 to stopping relay SR. The function of

the wattmetric relay WR2 is reduced to determine only the intensity of a stopping current for control of overload stopping relay OSR.

Synchronous commutator SC3 has two conducting and two insulating segments alternately spaced about its circumference. Brushes 392 and 393 are connected on the first half of each cycle. Brushes 392 and 394 are connected on the second half of each cycle. The synchronous commutator is shown on the first half of a cycle, and reverse switch 60 is shown in position for car movement from left to right in which position relays AR1 and SR1 are in control. The first half of each cycle is again positive for movement from left to right and negative for movement from right to left.

As shown the car can receive an accelerating current from pantograph 24a through filter 320a, brushes 392 and 393, rectifier 395, relay AR1, current coil of wattmetric relay WR2, dynamo ACD, to ground; as when a similar car is traveling in the same direction at a higher speed within the zone of control except when that car is forward and the control current is blocked by a synchronous trackway rectifier. Or the car can receive a stopping current passing from ground through dynamo ACD, current coil of WR2, relay SR1, rectifier 397, brushes 393 and 392, filter 320a, to pantograph 24a; as when a similar car within the zone of control is traveling in the same direction at a lower speed except when that car is following and the control current is blocked by a trackway synchronous rectifier or if the other car is traveling in the reverse direction at any speed except when behind and the control circuit is blocked by a trackway synchronous rectifier. Likewise if the car of FIGURE 12 were traveling in the opposite direction the reception of an accelerating current (positive current) on the second half of each cycle would pass through relay AR2 and the reception of a stopping current (negative current) would pass through relay SR2 on the second half of each cycle. Though the full cycle is always passed by this control circuit of the car, only the second half is used when traveling from right to left with respect to the closing of relays AR and SR, since the position of reverse switch 60 determines whether AR1 and SR1 or AR2 and SR2 are in control. The back contacts of relay SR are bypassed through front contacts 404 of relay OTR in series with normally open contacts 405 of switch 80 to select the stopping delay of relay OTR.

The remainder of the car's control circuits and their operation are substantially similar as described with FIGURES 2 or 5, and the same parts are designated by the same reference symbols for back reference. This vehicle is suited insofar as is shown for operation over the control blocks of FIGURES 5, 7, 8, and 12.

The synchronous commutator used on the car of FIGURE 12 together with rectifiers optionally can be used as a synchronous rectifier along the trackway as shown between blocks A6 and B6, FIGURE 12. This synchronous rectifier comprises a commutator SC4 (similar to SC3) driven by a synchronous motor SM4 which can be connected in series with a synchronizing frequency (60 cy.) pass filter 406 from the D.C. traction conductor 14a to ground. Block A6 is connected to block B6 through brushes 393' and 392' engaging commutator SC4 and rectifier 397' arranged to pass current from block A6 to block B6. Block A6 is connected to block B6 through brushes 394' and 392' engaging commutator SC4 and through rectifier 398' arranged to pass current from block B6 to block A6. The brushes and commutator are similar and are arranged similarly as those on the car. The commutator is so driven and arranged as to cause alternate half cycles of the control current from a rearward to a forward car to be passed by alternate rectifiers and to block control current from a forward to a rearward car for either direction of traffic. A.C. control current is passed or not passed depending on its phase relative to which rectifier is connected by the commutator on alternate half cycles. Brushes 392' are electrically connected

to block B6 in series with back contacts of a block bridging relay BRx. Brushes 393 and 394 are electrically connected through front contacts of relay TCR1 whereby rectifiers 397' and 398' are connected in parallel for two-way control signaling. D.C. traction power is fed through chokes 408, and A.C. synchronizing current is fed through filters 409 to each block.

Referring to FIGURE 13, a voltage divider can be substituted for dynamos DYN or ACD. The resistance terminals of rheostat 414 are connected across power line 416 and the rails. Automatic car controls as described herein are connected across control line 14 to the sliding contact 417 of the rheostat and so to the ground in series with the low voltage side of the potentiometer thus formed. The sliding contact of the potentiometer is arranged to be turned from the low voltage end of the potentiometer at which it rests at zero car speed to positions of higher voltage the higher the car speed. Means such as speed governor 418 driven from the car axle 420 controls the position of contact 417 whereby the voltage inserted in series with the automatic controls represents car speed. Traction power can be either A.C. or D.C. With A.C. current supplied across resistance terminals of rheostat 414 the polarity can be reversed for reverse direction of travel by connecting one coil of transformer 422 in parallel with the low voltage resistance portion of the potentiometer and connecting the other coil of the transformer reversibly in series with the car controls ACC by means of contacts on reverse switch 60.

Referring to FIGURE 14, a problem of supplying A.C. traction power to the cars on a D.C. control line is shown. D.C. dynamo DYN is connected in series with A.C. choke coil 424 and automatic car controls ACC across the trolley and rails. The A.C. power transformer 426 is connected across the trolley and rails in series with a large capacitor 428. Each block section of the combination power and control line 14a is fed A.C. traction current through large condensers 430. The size and cost of the condensers are excessively great but not impossible. Therefore an arrangement such as shown in FIGURES 5, 40 9, or 12 is preferred.

Referring to FIGURES 15 and 16 for another variation of the train control circuit whereby a unit can be uncoupled at speed from a train anywhere along the trackway and be slowed without slowing the train or disrupting the safety features of the control circuit, along track 10h on which are shown cars 20h and 22h, FIGURE 15, are run two control lines 14d and 14d' divided respectively by insulators 18d and 18d' into coextensive block lengths of which block B7 and portions of A7 and C7 are shown. Across lines 14d and 14d' at the left-hand end of each block is connected block supply battery 432 with positive to line 14d in series with red signal light R and A.C. choke 434. Across the right-hand end of each block is connected the coil of block circuit relay BR9 in series with A.C. choke 436.

Between adjacent blocks, insulators 18d and 18d' are arranged to be bypassed through respectively back contacts 438 and 438' on the relay BR9 connected across the left-hand block. Each contact 438 and 438' is in series with two rectifiers 26d one on each side of the contact. Both rectifiers in series with each contact are arranged to pass control current from left to right from block to block on a control line 14d or 14d'. An electrical connection 442 is made from the left-hand side of contacts 438' to the right-hand side of contacts 438 between adjacent blocks, whereby control current can pass from line 14d' to line 14d of the adjacent block on the right without the blocks being bridged together by the relays, whereby the zone of control is extended two extra blocks between trains. This zone of control varies from three to four blocks using only the lines 14d and 14d' therebetween.

Each car has a check circuit and a control block shorting circuit connected in series across trolleys 24d and 24d' engaging respectively lines 14d and 14d' and comprising

from trolley 24d, rectifier 444, coils 446 and 447 of differential check relay CR' in series aiding, rectifier 450 in parallel with back contacts of relay COR'. Rectifiers 444 and 450 are arranged to short the control blocks, i.e. 5 pass check current from battery 432 through the coils of relay CR'.

Dynamo DYN is connected in series with automatic car controls ACC and A.C. choke 58 from a point between the coils of check relay CR' to the rails to complete the 10 intertrain control circuit on the car from trolleys 24d and 24d' to the rails. The rails complete this control circuit between trains within the zone of control. Of course DYN could be replaced with ACD if rectifiers, filters, etc. are appropriately changed or added as taught with FIGURES 5, 9, and 12.

When unit 22h, FIGURE 15, is uncoupled from train 20h traveling to the right, relay COR' opens the bypass about rectifier 450 on unit 22h, whereupon this rectifier blocks the receiving of an accelerating current from line 20 14d' and rectifiers 444 on both the uncoupled unit and the forward train block control current on line 14d therebetween; whereby, whether the uncoupled unit is in the same block or a different block within the zone of control while relay COR' is energized, the slower moving unit has 25 an open control circuit relative to the train ahead; whereby the slowing of the unit does not reduce the speed of the train. Such a train approaching the uncoupled unit 22h in another block behind (not shown) within the zone of control will pass control current to line 14d', connection 30 442, line 14d to trolley 24d of the uncoupled unit and through rectifier 444 of this unit, whereby the approaching train is slowed.

Check relay CR' is held open by the block circuit current passing from trolley 24d to 24d' indicating that the 35 trolleys are in good contact and that the control lines of the block circuit are not broken or shorted out. The check circuits of the cars have sufficient resistance so that the block circuit can hold open the check circuit relays CR' on as many trains as might enter the block, yet low enough so that one train will sufficiently short the control block to drop BR9 therein.

The two-way control-closing alternator F1' is connected 40 across trolleys 24d and 24d' in series with operator's switch 80 and capacitor 452. Two-way signaling closing relay TCR3 has front contacts arranged to bridge block sections of lines 14d and 14d' separately together and has its coil 45 connected in series with condenser 454 across lines 14d and 14d' so as to be energized by alternator F1' when the operator desires to catch a unit ahead.

Where there are double rail track circuits used for clear 50 track indications or other purposes the usual trackway blocks AT and BT are bridged by rectifier bonds such as shown at the right of FIGURE 15. This rectifier bond comprises two rectifiers 456 in series connecting adjacent insulated rail ends of both rails 11h and 12h. The rectifiers are arranged to pass current from right to left. Connection is made between rectifiers in each bypass by conductor 458. Return control current (and traction current of the proper polarity) can be passed by this rectifier bond. One rail insulator 36h is bypassed for two-way control return current through front contacts 459 of relay 55 TCR3 between blocks B7 and C7.

A more complete vehicle circuit hookup of the two-control-line intertrain control circuit is shown in FIGURE 65 16, wherein the intertrain control circuit comprises from line 14d, trolley 24d in series with back contacts 460 of relay 180d both in parallel with trolley 24d' in series with back contacts 460' of relay 180d', train line 56d, segment 57 of reverse switch REV, contacts 86 on coupling switch CS or CS' whichever is at the front of the car, line 88, back contacts of relay COR'' in parallel with rectifier 444 arranged to pass current from line 14d, and coil 446 of relay CR' all in series; and from line 14d', trolley 24d' in series with back contacts 460' of relay 180d, train line 56d', segment 57' of reverse switch REV, contacts 86' on 70 75

coupling switch CS or CS' whichever is at the front of the car, line 88', back contacts of relay COR' paralleled by rectifier 450 arranged to pass current to line 14d', and coil 447 of relay CR'; from a point between coils 446 and 447 in series, choke 58 to point J wherefrom to ground the control circuit is similar as shown in FIGURE 2 except that the coil of relay 462 is added across the pull-in coil of relay OTR and certain items are omitted for clarity, but it should be understood that omitted items can be added in various showings to provide desired features.

Relay COR' is energized as explained with FIGURE 2 and as again shown in FIGURE 16. Relay COR'' is energized for the delay period of time delay relay TDR' which preferably has a time delay after being energized until opened approximately equal to that of relay TDR. Relay TDR' is energized through a circuit from the positive of battery 96 including in series segment 464 of reverse switch REV, contacts 466 of coupling switch CS' or CS whichever is at the rear of the car, line 468, coil of relay TDR' to ground. The circuit for energizing relay COR'' comprises in series from line 468 back contacts of relay TDR', line 470, coil of relay COR'' to ground. Line 470 is connected by line 471 to a train line whereby relay TDR' energized on the rear of a train from which a unit has just uncoupled closes current from battery 96 on the rear car through the train line connected by lines 471 on all cars whereby relay COR'' is energized on the forward car (and all cars). By this arrangement relay COR'' is opened on the lead car of a train from which a unit has uncoupled from the rear.

The addition of the bypass around rectifier 444 closed through back contacts of relay COR'' causes a train having COR' closed and following an uncoupled unit in any block within the zone of control to be stopped by the stopping of the uncoupled unit; and yet, since rectifier 444 blocks the signal of the train from line 14d when relay COR'' is opened on the train from which a unit has just uncoupled, the forward train is not slowed by the stopping of the unit uncoupled from its rear.

With such an arrangement it is preferred that the unit be permitted to uncouple from a train at speed only when there is no train within the zone of control ahead. This can be checked by requiring a clear track signal before permitting uncoupling; or this can be checked by separating the trolleys 24d and 24d' from 24d'' and 24d''' respectively and by connecting whichever are at the front of the train from the control circuit to a circuit which checks for the absence of signal, whereby it is determined that there is no moving car ahead, and by checking against a stopping current in the control circuit closed by the rear trolleys it is determined that there is no standing car ahead except when the train is standing, when it is of course safe to uncouple a unit from the rear. Relay 180d or 180d' when energized disconnects the forward trolleys 24d and 24d' or 24'' and 24''' respectively whichever are at the front of the front car from the control circuit of the train. Relay 180d or 180d' is energized from line a' in series with segment 174f, contacts on coupling switch CS or CS' respectively, lines 476 and 477 respectively to the coil of relay 180d or 180d' to ground, whichever is at the front of the front car. Front contacts of relay 180d and 180d' connect each trolley preferably through a resistive impedance 478 to the coil of relay 182, which when energized opens line b as in FIGURE 2. Line b is now connected by front contacts 179 or 179' of relays 180d and 180d' respectively to line 476 and 477 and so to line a'. Contact 179 or 179' closes the circuit of line b after the other front contacts of relay 180d or 180d' have closed, so that relay 182 is opened before contact 179 or 179' closes if a control current is received. Line b is connected through back contacts of relay 462 which is energized and opened by a stopping current to prevent the closing of the uncoupling circuit when there is a standing train or car ahead, which would not send a signal to lift relay 182.

When an operator closes switch 170 to uncouple a unit from a train relay 180d or 180d', whichever is at the front of the train, is lifted closing contacts which connect relay 182 to the control lines wherefrom relay 182 is energized if there is a moving train ahead within the zone of control or if the train on which switch 170 is closed is traveling and the trolleys at opposite ends of the first car are connected on the same section of control conductors. After relay 182 has had time to lift contacts 179 or 179' whichever are at front close. When a trackway control circuit rectifier separates trolleys 24d and 24d' from 24d'' and 24d''' on the front car of a train whereon an operator holds switch 170 closed with no moving train ahead within the zone of control relay 182 drops. The uncoupling circuit is completed when relay 182 drops with relay 462 deenergized and contacts 184 and 186 closed.

A variation of the automatic car controls is shown in FIGURE 16 whereby notches of the operator's control drum are paralleled by a series of contacts of accelerating relays, and a series of stopping relays are arranged to open the circuits closed by the operator's drum or by the accelerating relays in the reverse order of closing. Control power from any suitable source, such as the positive of battery 9, is connected to segment 232 on reverse switch REV, wherefrom it is connected through coupling switch battery 96, is connected to segment 232 on reverse switch position checking contacts and through them to drum K. Controller K connects power to notch lines j, k, and l in the usual manner and connects power to automatic control supply line 480 in all positions except "reverse" by means of segment 482. Front contacts of relay AR connect power from line 480 to coils of accelerating relays U1, U2, U3, and U4 in succession, each relay above U1 through front contacts 484 of the preceding. Relays U1, U2, U3, and U4 each have a holding coil and front contacts 485 through which power is connected from line 480 to lines j, k, l, and m respectively, whereby the energizing of relay AR closes relays U1, U2, U3, and U4 in succession preferably with time delay between the closing of each relay, whereby as the car accelerates relay AR can open and leave one or more relays of U1 through U4 held closed through their holding coil. Thus power is connected to lines j, k, l, and m through controller K or in parallel through front contacts on a U-series relay of the automatic accelerating control. Lines j, k, l, and m are connected each to their train line through front contacts 486 of relays D4, D3, D2, and D1 respectively. Power from line 480 is connected in series through back contacts of relays SR, OSR, and USR to a coil on each of relays D1, D2, D3, D4, and D5 in parallel. Power is connected from line 480 through the top coils of relays D2, D3, D4, and D5 each respectively in series with lower front contacts 487 of relays D1, D2, D3, and D4 and front contacts of relays F1, F2, F3, and F4. Relays F1, F2, F3, and F4 have their coils respectively connected from line m, l, k, or j on the train line side of contacts 486 to ground (optional to having them in series with their supply line). The opening of any relay SR, OSR, or USR will drop relay D1; deenergize the lower coils of relays D2, D3, D4, and D5; and drop the D-series relays whose top coils are not energized. The highest numbered D-series relay whose top coil is not energized opens immediately, so that no matter to what notch the U-series relays have closed a stopping current immediately opens the highest line j, k, l, or m closed. The F-series relay energized by the highest closed line j, k, l, or m then is dropped opening the circuit of the top coil of the next lower line j, k, or l closed etc. Relays F1, F2, F3, and F4 are preferably time delay relays allowing time for the reduction of power to the traction motors to reduce car speed before opening the circuit to the next D-series relay to open. Lines m, l, k, and j are thereby opened in succession from the highest closed with time delay between the opening of successive controller lines or notches. The

opening of front contacts of relay D5 applies the brakes by deenergizing solenoid valve 470 which controls the brakes. Various degrees of braking can be applied by additional relays which will close after relay D5 to apply brakes more strongly if the top coils of the D-series relays remain deenergized, and additional relays SR' and OSR' respectively in parallel with relays SR and OSR could open all lines *m*, *l*, *k*, and *j* and apply the brakes when energized by a stronger stopping current than relays SR and OSR.

Various additional check circuits can be provided throughout so that a complete check of the control circuit can be had. Check circuits can overlap, and various check circuit frequencies can be used.

Having thus described a few of the many and various forms of my invention, I contemplate to cover by the appended claims all variations which fall within the true spirit and scope of this invention.

I claim as new and of my invention and desire to secure Letters Patent on:

1. A railway speed control system comprising in combination: a stretch of trackway; a first and a second vehicle thereon; a first and a second electrical conductor running parallel said trackway, said first being sectionalized; rectifiers connecting adjacent sections of said sectionalized conductor to pass current simultaneously in one direction only therewith; contacts in series with said rectifiers between adjacent groups of said sections to define blocks; means controlled by the approach of a vehicle on said trackway for controlling said contacts to connect all adjacent blocks between vehicles only when those vehicles are within a predetermined distance apart on said trackway; electrical means on each said vehicle for providing a voltage reversing in polarity sequence when the vehicle is operated in reverse and representing by its open circuit voltage output the speed of the vehicle equally on each said vehicle; control circuit and moving contact means connecting each said electrical means across said conductors; a reverse switch on said first vehicle and means to position said switch according to direction of vehicle movement along said stretch of track; and means including current operated polarized automatic control means for accelerating and decelerating said first vehicle according to the direction of the control current and connected on said first vehicle by said reverse switch in series with said electrical means across said conductors, said reverse switch connecting said control means in said circuit in such a direction that said first vehicle is decelerated when operating faster than said second vehicle when connected thereto by said conductors, said rectifiers being positioned to pass current between said vehicles when approaching from opposite directions and when moving in the same direction with the faster vehicle in the rear.

2. In a system as claimed in claim 1, on said first vehicle, an electric drive for said vehicle, traction power contact positioning means connecting power to said drive gradually for accelerating the vehicle when energized and for decelerating the vehicle when deenergized, said control means having accelerating contacts closed by an accelerating current in the control circuit to the vehicle and having decelerating contacts opened by a decelerating current to the vehicle, an accelerating circuit including operator switch means connected in series with said decelerating contacts and said positioning means across the power source to energize said positioning means to accelerate the vehicle, a second operator switch means, said accelerating contacts being connected in series with said second switch means across said first operator switch means.

3. In a system as claimed in claim 2, delay means connected to said control circuit for delaying deceleration of said positioning means initially energized only by a strong stopping current which results when the control circuit is first completed between approaching vehicles,

and check means operated by movement of the vehicle and the stopping current for limiting the delay of said delay means inversely according to the drop of the control current in said control circuit against distance traveled by said vehicle after the closing of said intertrain control circuit.

4. In a system as claimed in claim 1, on said first vehicle, electrically controlled uncoupling means, an operator's uncoupling switch for controlling said uncoupling means, check contacts and means for closing said contacts only when the track to the rear of the vehicle is clear of said second vehicle to a safe distance, said uncoupling means being connected across the power supply in series through said operator's switch and said check contacts.

5. In a system as claimed in claim 1, a trackway and vehicle check circuit including a check current supply connected across said conductors in each said block, a check current path on each said vehicle including the portion of the control circuit to be checked, means for detecting the presence of a vehicle in a said block and means controlled thereby and by said check circuit for warning approaching traffic of the presence of a vehicle occupied block which has an open check circuit.

6. A railway speed control system comprising in combination: a stretch of track comprising a first and a second rail electrically insulated from each other; a control conductor paralleling said track; insulators dividing a rail of said track and said conductor into corresponding lengths called track circuit blocks and control blocks respectively; current source means connected across said rails of each said track circuit block; rectifiers; a plurality of relay means each having contacts in series with a said rectifier similarly connected across adjacent said control blocks and having coil means for controlling said relay means connected across said rails of the corresponding said track circuit to be energized from the said current source means which is connected across the rails of that block to open said contacts when the track is clear; trains on said track each shorting said rails of all track blocks the trains are in; a current path including in series on each said train, a current collector engaging said conductor, a first signal current source for providing an open circuit voltage representing the train's speed and having a polarity representing direction of the train's movement on said track, and current direction sensitive speed control means connected in series with said source from said collector to said track for controlling the speed difference between trains within a predetermined distance apart, said rectifiers being connected relative to the polarity of said signal source to pass the current of the control circuit when the faster train is at the rear.

7. In a system as claimed in claim 6, a differential check circuit for checking the completion of the control circuit in a block and comprising in combination: a second current source providing a different frequency from said first, a differential relay having a first and a second coil between the rail and control conductor, a first and a second filter for attenuating current of said first source and passing current of said second source, said first filter and first coil being connected in series from a rail of a track block to said conductor in the coextensive control block, said second filter in series with said second coil being connected from the rail in the same track block to said conductor in an adjacent block, said second supply being connected in series with a said filter and coil for passing current around said check circuit, and second contacts operated by said coil means to close when said coil means is deenergized as by the shorting of the rails of the track block across which the coil means is energized, and third contacts on said differential relay opened when a vehicle passes check current through a said current path and a coil of the differential relay, and a circuit completed through said second and third contacts in series and including means for signaling to any ap-

proaching said train a warning signal if this last mentioned circuit is closed.

8. In a system as claimed in claim 7, said contact means carried by said trains being arranged to engage said conductor at each end of the train endward of the train from the end rail-shorting axle, said track circuit and control blocks being substantially coextensive so that said trains draw check current before, during, and after shorting each said track circuit block.

9. In combination in a speed control system, a vehicle way, vehicle units adapted to operate therealong, a control circuit including: a plurality of electrical conductors paralleling said way, control circuit means on each said vehicle unit electrically connected across said conductors and arranged for moving contact thereon and having in series therein electrical means for providing a voltage variable with vehicle speed to represent vehicle speed with a particular open-circuit voltage and vehicle direction along said way with a particular polarity, and polarized automatic accelerating and decelerating means connected in series with said electrical means to control acceleration and deceleration of the vehicle unit according to the direction of current in said circuit, at least one said conductor divided into lengths, rectifier means, relay means having contacts connected in series with said rectifier means across adjacent said lengths of the same conductor, control means controlled by the presence of the vehicle for closing said relay contacts to close the control circuit between said units when within a predetermined distance apart allowing said automatic means time to balance out speed differences between said vehicles before the vehicles meet, said rectifier means being arranged to pass control current between approaching vehicles and block it between receding vehicles.

10. In a control system as claimed in claim 9, each said electrical means comprising a dynamo having a full main field with zero armature current, a series field on said dynamo opposing the main field similarly on each said unit to limit maximum current.

11. In a combination as claimed in claim 9, a bypass arrangement having switch means therein connected in parallel with said rectifier means and means for controlling said switch means to close for a distance ahead of a said vehicle unit so that control current can pass in either direction past said rectifiers between vehicles, and means for selectively closing said switch means from a said vehicle unit to permit a rearward vehicle unit to slow a forward unit to couple with it.

12. In a control system as claimed in claim 9, said way including a railway track, one of said conductors being said track, said track having two rails insulated apart and divided into track circuit blocks, center-tapped impedance coils connected across said rails at each end of the blocks, a parallel resonant circuit including a choke coil and a condenser connected in parallel across center taps of said coils at adjacent block ends to attenuate the control current from passing from block to block and yet pass traction current, said relay means having contacts connected across said resonant circuit and controlled by said control means to close upon the approach of a train to complete the control circuit a safe distance between trains.

13. In combination in a speed control system, a vehicle way, vehicle units thereon, a plurality of electrical conductors paralleling said way, a control circuit on each said vehicle unit electrically connected across said conductors and arranged for moving contact thereon, electrical means on each said vehicle unit for providing a voltage representing vehicle speed and having a polarity dependent on the direction of vehicle operation, reverse switch means and polarized decelerating means reversibly connected by said reverse switch means in said control circuit and so arranged that the polarity of the control current relative to the position of the reverse switch determines when said decelerating means are energized by

said circuit to operate similarly on each said unit, at least one said conductor being divided into lengths and rectifier means connecting adjacent lengths of the conductor, said rectifier means being arranged to simultaneously pass current in the same direction around the control circuit, and to pass control current between said vehicle units when approaching but not when receding.

14. In combination, a railroad track having a series of track circuit blocks each including a track circuit current supply and a track circuit relay connected in parallel across the rails of the track to be shorted by the presence of a train, control blocks comprising lengths of conductor insulated apart and extending end to end parallel said track and each substantially corresponding in length and location to a said track block, relay contact means controlled by said track circuit relay for electrically connecting said control blocks in the vicinity of a shorted track circuit block to complete an intertrain control circuit, a differential check circuit comprising a differential relay having a first and a second coil, two control current attenuators for blocking the control current and for passing the check current, a check current supply connected from a track block to a control block thereat in series with a said attenuator and said first coil of said differential relay, the other coil of said differential relay being connected from the same track block to the adjacent said control block to the right in series with the other said attenuator, a vehicle on said trackway shorting the rails thereof and having a control circuit path thereon for passing a check current from said supply to the track block and through said first coil to unbalance said differential relay, and means controlled by the unbalance of said differential relay to indicate to other vehicles that the shorting vehicle has a completed control circuit.

15. A railway speed control system comprising in combination a length of trackway, two vehicle units thereon, electrical conductive means paralleling said length, a return current path paralleling said length, a synchronous motor on each of said units, an alternating current supply and circuit means connecting said supply to said motors, separately excited alternating current dynamos each connected to be driven from a said motor to provide a frequency output a whole multiple of the pairs of poles in the motor and in phase together on each of said units, an exciter driven at a speed proportional to vehicle speed and connected to supply direct current to the main field of the said dynamo on each said vehicle unit for providing a voltage output with each of said dynamos representing the vehicle's speed, an intertrain control circuit path connected on each said vehicle unit across said conductive means and said return path to form a closed circuit between said vehicles, the output of each said dynamo being connected in series with said path on its unit, and means in said control circuit for indicating which vehicle is traveling the faster.

16. In a signaling system a control conductor divided into a series of several segments, rectifier means connecting all adjacent segments of said series so as to simultaneously pass current in the same direction between segments, contacts and a second conductor in series connected across the segments at opposite ends of said series, a third conductor paralleling said segments, a first and a second vehicle having a polarized control circuit completed therebetween through a plurality of said segments and said third conductor as a return path, whereby control current blocked by said rectifiers between the vehicles can be passed from any segment to any segment around the loop circuit formed with said second conductor when said contacts are closed and means for controlling said contacts to vary conditions of control between vehicles.

17. A railway speed control system which comprises in combination: a track; control conductor means running parallel with said track; cars on said track having collector means contacting said control conductor means, a current path from said collector means to the track and

including speed control means and electromotive means providing a voltage representing the speed and direction of said car along said track, said voltage having simultaneously the same polarity at said collectors on all said cars moving in the same direction along said track and having the opposite polarity for all cars moving in the opposite direction thereon whereby a control current circuit is established between cars through the track and said conductor means, and trackway rectifier means limiting the current in said control circuit to such a direction that the control circuit is established between said cars only when they approach each other, and means useful in controlling a said car actuated by a current in said control circuit.

18. A speed control system having in combination, a track, control conductor means comprising a plurality of adjacent sections of conductor running in succession parallel with said track, railway vehicle units traveling in the same direction on said track, current collectors on said units contacting said conductor means, circuit means on said units connecting said collectors and the track and including: electromotive means similarly arranged on each said unit to provide a voltage proportional to that unit's speed, current direction selective speed control means in series with said electromotive means, the track serving as a return conductor in the control circuit, and rectifier means connected across adjacent said sections and arranged to limit the direction of control current along said control conductor means.

19. In a control system as claimed in claim 18, means reversing the polarity of said electromotive means with reversal of direction of unit movement on the same track and reverse switch means for reversing current connections of said speed control means in said circuit means whenever the unit is operating in the reverse direction on the same track.

20. A speed control circuit which comprises, a first and a second parallel conductor insulated apart, said first conductor comprising sections, rectifiers electrically connected and arranged to pass current simultaneously in the same direction across said sections, vehicles arranged to run parallel said conductors, and a current path connected across said conductors on each said vehicle and including in series: voltage supply means on each said vehicle and including means to vary the voltage with and to represent the vehicle's speed in a given direction and having a polarity representing the vehicle's direction along said conductors, and speed control means in said control circuit for detecting current in said control circuit, to determine whether vehicles are approaching or separating when separated by one or more of said rectifiers.

21. In a control circuit as claimed in claim 20, relays having front contacts connected across said rectifiers, signal and circuit means for controlling said relays from a vehicle to close said contacts to permit control current to pass in either direction between vehicles selectively, said control means including means for detecting current direction for accelerating or decelerating the vehicle according to current direction in said current path on that vehicle.

22. In combination, a low impedance current conductor paralleling a vehicle route divided into lengths, rectifier means, relay means, low impedance conductive means connecting successive lengths of said conductor in series with said rectifier means and contacts of said relay means, circuit means for controlling said relay means to connect a series of said lengths in the vicinity of a vehicle, said rectifier means being arranged to pass current in the same direction at the same time from length to length between trains within the range of connected said lengths and at the same time block current from passing in the opposite direction from length to length along said conductor.

23. In combination with a first and a second parallel conductor each having a block limiting insulator dividing each conductor into two lengths to limit a railway block

circuit; a rectifier bond for connecting control current across said insulators without electrically connecting a block circuit of the block to the adjoining conductors and comprising: four rectifiers, a first conducting means connecting two said rectifiers in series across a said insulator, a second conducting means connecting the other two said rectifiers in series across the other said insulator, said first and second conducting means being electrically connected at a point separated from each end of both said conductors by a said rectifier, said rectifiers being arranged to pass current in one direction across said insulators, whereby current of the proper polarity can pass from one said conductor to both said conductors in an adjoining block, while all current is blocked from passing between said first and second conductor in the same block.

15 24. In a rectifier bond as claimed in claim 23, relay means, two sets of contacts thereon, one connected in series with said first and the other connected in series with said second conducting means between said rectifiers 20 therein and on opposite sides of said point, means controlled by trains along the route for operating said relay means to close said contacts in the vicinity of a train whereby the zone of control is extended one block by the relay and one block through said point from one 25 said conductor to the other, the point being located so that current can pass from said first to second conductor and so that said rectifiers prevent current from said second to first conductor while said relay is energized.

25 26. A railway speed control system having in combination, track, track circuit blocks therealong, control conductor means paralleling said track, control conductor blocks therealong, insulating means separating said blocks and relay means having contacts connected across said insulating means to bridge said blocks together, said 30 relay means being controlled by said track circuits to close said contacts between a plurality adjacent blocks, in the vicinity of and by the presence of a rail vehicle shorting a said track circuit block, and rectifier means in series with said contacts for limiting control current between rail vehicles to a given direction of current along said control conductor means.

35 27. In a speed control system having a conductor paralleling a vehicle route and divided into blocks that are to be electrically bridged together upon approach of a vehicle for speed control thereof, relay means for bridging adjacent blocks of said conductor in the vicinity of a train, contacts on said relay means connected across adjacent blocks, a check circuit comprising a source of electromotive force and a signal device connected in series across the contacts of said relay means which bridge said blocks to check the bridging of the blocks together upon the approach of a vehicle on said route.

40 28. A railway signal system which comprises: a track; a power supply conductor paralleling said track; double-rail track-circuit blocks along the length of said track; relay means controlled by said blocks and having contacts connected to bridge each shorted track circuit block to a number of adjacent blocks; an alternating current supply connected to said power supply conductor; rail 45 vehicles on said track each having thereon a current collector contacting said conductor; a circuit including a frequency filter arranged to pass the frequency of said supply and attenuate other frequencies, and a synchronous motor in series therewith across said collector and said track; an alternating current dynamo having a separately excited field; said dynamo being connected to said motor so as to be driven thereby in step and provide a frequency a whole plural multiple of the frequency supplied to said motor; means supplying a current variable with car speed to the field of said dynamo whereby the voltage of said dynamo represents a particular car speed; a wattmeter having its voltage coil connected across output terminals of said dynamo; a current path including a frequency filter arranged to pass the frequency of said dynamo, the 50 55 60 65 70 75

current coil of said wattmeter, and the armature of said dynamo connected in series across said conductor and the track; a control circuit which includes two said current paths connected by said supply conductor and said track when two said vehicles come within a predetermined number of blocks apart; a circuit current resulting from a voltage difference between said dynamos in said control circuit; whereby the displacement of each said wattmeter in said circuit indicates the speed difference between two said vehicles through which the control circuit is completed for control purposes.

28. A railway control system which utilizes a motive power contact conductor for speed control signaling between trains and comprises, a trackway, a paralleling collector-riding conductor of low impedance divided into sections, a motive-power supply, means for electrically connecting said motive-power supply to each said section and for blocking control signaling power from passing therethrough from section to section.

29. A speed control system having in combination a contact conductor divided into lengths and a return conductor parallel a vehicle route, insulating means supporting and insulating the lengths of said contact conductor apart arranged whereby contact means on vehicles can run from length to length along said contact conductor, a power supply line, power and control frequency supply means connected across said supply line and return conductor, relay means having front contacts connected across adjacent lengths of said conductor, circuit means including control frequency selective means connecting each said length of said conductor to said power supply line in series with a coil of said relay means to pass the control current to operate the relay means and block the power current, and impedance coils connecting said power line to the lengths of said conductor for passing traction power from the supply line to said conductor and for blocking the control current from passing from one length of said conductor to another, and vehicles and circuit means completing the circuit which energizes said relays so that blocks are bridged together so as to pass alternating current between vehicles within a limited range.

30. In combination, a vehicle way, a sectionalized running contact conductor the sections thereof being insulated apart and run along the vehicle way, relays having back contacts, bypasses connecting adjacent lengths of said conductor each through back contacts of a said relay, a supply conductor, a return conductor, power supply means connected from said supply conductor to said return conductor, means to pass current of said supply and block current of different frequency connected from each said section to said return conductor in series with the coil of the said relay whose contacts connect to the section to the right to said return conductor, resistance means and means to pass current of said supply and block current of a different frequency connected in series from each said length of said contact conductor to said supply conductor, vehicles on said way and circuit means on each said vehicle connected from said contact conductor to said return conductor so as to short the length of said contact conductor at the vehicle sufficient to drop the said relay connected through that length of said contact conductor, to connect said sections between said vehicles when within a predetermined number of sections apart.

31. In a combination as claimed in claim 30, the resistance of said resistance means being a high enough resistance relative to the shorting impedance of the vehicles and the resistance of the relay connection between blocks so as to drop a series of said relays in adjacent blocks by the shorting of one block.

32. In combination, two lengths of a combination power and control circuit conductor insulated apart, a power supply, a power-feeding and control-blocking impedance comprising a core, three coils of the same number of turns on said core, two said coils being connected in

series aiding across said lengths, the third coil being connected from said power supply to a point between the other two said coils in such a direction as to oppose the flux of the other two said coils.

5 33. In an intertrain control circuit wherein control current is transmitted over traction current conductors having a control circuit path in parallel across the traction power supply conductors, means blocking the traction current from a portion of the control circuit on said vehicle which means comprises in combination, a motor-generator set, a control current attenuators, the motor of said set operating from traction power supplied at the vehicle in series with said attenuator thereon, the generator of said set being connected in series with the portion of the control circuit and driven for bucking the traction voltage with a substantially equal and opposite voltage to block traction power from the portion of the control circuit.

20 34. A synchronous device for polarizing an alternating control circuit to limit control current to a given direction on alternate half cycles and comprising, current directional selective means to conduct current in one direction only, a high speed switch arranged to open and close a circuit alternately for substantially equal periods of time, 25 a synchronous motor connected to drive said switch in step therewith to open and close contacts of said switch for alternate half cycles of the frequency of the circuit to be polarized, said switch being in series with said selective means to pass or not pass current in one direction on alternate half cycles of said control current according to the phase of the control current relative to the position of said switch.

35. A synchronous device for polarizing an alternating current circuit, comprising in combination, a commutator 35 having rectifier means connected across and secured to electrically opposite segments of said commutator reversely from adjacent segments.

40 36. In an alternating-current speed control system, an arrangement for determining whether a track guided vehicle is to be automatically accelerated in a given direction, which comprises in combination: an alternating-current control circuit in which the phase of the control current indicates direction of movement of vehicles; a first switch in said circuit and means for controlling said switch to open and close at least a portion of the control circuit for successive half-cycles of the control current, a rectifier, a reverse switch having contacts reversibly connecting said rectifier in series with said first switch, said contacts being reversed when the vehicle is operated in reverse direction on the track; and electrically controlled means by which the vehicle is operated, said means being connected in series with said first switch and said rectifier; said first switch, reverse switch, and rectifier determining the polarity of successive half cycles of 50 the control current to be passed through said electrically controlled means, and arranged to pass current when the phase of the control current indicates it is safe to accelerate the vehicle in the direction indicated by said reverse switch.

60 37. In a speed control system an arrangement for determining whether a car is to be automatically accelerated in a given direction upon approach of a train and comprising on a railway car in combination: a switch in the form of a commutator including a first and a second brush set engaging electrically connected portions 65 of said commutator and alternately for substantially equal arc portions insulated apart, a synchronous motor connected to drive said commutator, an alternating-current intertrain control circuit in which the phase of a control current on a car represents whether the car is the fastest or a slower moving car for a given direction of traffic within a control zone, said commutator being so positioned and driven by said motor at such a speed that said first and second brush sets are alternately connected in phase with the current of the control circuit

to pass every other half cycle of control current across brushes of the first said brush set and opposite half cycles across brushes of the second set, rectifiers oppositely connected in parallel with each other and both in series with said first brush set, accelerating relays the coil of one connected in series with brushes of said first set and a said rectifier and in parallel with the opposite said rectifier, the coil of another said relay connected in series with brushes of said second set and the rectifier connected to pass current of 180 phase difference from that passed to the coil of the first relay, front contacts on said relays, a reverse switch and a third accelerating relay the coil of which is connected by said reverse switch through front contacts of either said first or second relay according to the position of said reverse switch whereby the position of the reverse switch determines whether a car should be accelerated according to the phase of the control current.

38. A speed control system for trains comprising in combination, a trackway, trains thereon, a synchronous motor and an alternating current dynamo connected together on each said train in such a relation that the dynamos are driven in step when the motors are supplied from the same alternating current supply, the dynamo developing a frequency a whole multiple of the frequency of said motor similarly on each train, a control circuit comprising at least two conductors running between said trains and the said dynamo of each train being connected across the same said conductors, means for supplying alternating current connected to each said motor in synchronization, means for controlling the voltage output of said dynamos to vary with train speed, and control means including current direction discrimination means in said circuit for substantially determining which dynamo is generating and which motoring for control purposes.

39. In a speed control circuit as claimed in claim 38, said conductors being traction power conductors, and filter means connected in series in said control circuit on each train to pass the control current and block the traction current from said control means.

40. In a speed control circuit as claimed in claim 38, insulating means dividing at least one said conductor into sections, rectifiers similarly connected across said sections to pass control current in one direction from section to section and a rectifier in series in the said control circuit of a vehicle of a said train, an electrical bypass about said second mentioned rectifier and contact means in series in said bypass to open said bypass whenever the vehicle has uncoupled from a train, said current direction discriminating means including a synchronous commutator driven in step with the output signal frequency of said dynamos with such a phase relation so as to pass the same alternate half cycles and block opposite half cycles of said signal frequency, said rectifiers being arranged to pass half-cycle current pulses between a train and an approaching rearward train.

41. In a control system having a sectionalized control circuit, a synchronous circuit polarizer comprising a rectifier and a synchronously driven on-off switch connected in series across adjacent sections of the control circuit and driven to block or pass an alternating control current according as the control current is in phase or 180 out of phase with the rectifier.

42. In a control system, in combination: vehicles; an alternator; a commutator; first, second, and third brush means engaging said commutator, and means for driving and synchronizing both at the same frequency on all said vehicles the same; means for varying the output of said alternator according to vehicle speed whereby said alternator develops a voltage representing vehicle speed; means for reversing the phase of said alternator with reverse of vehicle movement; parallel conductors between vehicles; and running contact means on each said vehicle engaging said conductors separately; a control circuit connected across said contact means engaging different said

conductors and comprising in series said first brush means; successive conducting segments of said commutator each alternately connecting said second and third brush means with said first brush means for alternate half cycles of said alternator; two sets of two parallel branches in said control circuit, each branch comprising the coil of a relay and a rectifier in series, each set having one said rectifier arranged to pass accelerating current and the other decelerating current between said alternators connected between vehicles, decelerating current being that passed through the alternator of the faster moving said vehicle, one terminal of one set being connected to said second brush means, one terminal of the other set being connected to the third said brush means, both said sets being connected in parallel with each other and in series with said alternator; a reverse switch having a plurality of contacts; means for automatically accelerating the vehicle; a circuit for controlling said last means to accelerate when energized and including back contacts of said relays which are connected in series with similarly connected said rectifiers being connected reversely through said reverse switch to accelerate the vehicle, each for operation of the vehicle in a different direction; means for decelerating the vehicle; a circuit for controlling said last means including contacts on the remaining said relays being connected reversely through other contacts on said reverse switch to decelerate the vehicle; said reverse switch being arranged to pass an accelerating current when set to accelerate the vehicle away from an approaching vehicle.

43. In a control system in combination, two vehicles, a tachometric generating device on each said vehicle providing an alternating voltage whose amplitude represents the speed of the vehicle on which located, the output of each said device being synchronized in phase, and means to reverse the phase when the direction of movement is reversed, exposed and insulated apart parallel conductors between said vehicles, two running contacts on each said vehicle, each engaging one of said conductors, current direction discriminating speed control means and a commutator-like switch having contacting brush means all connected in series with said device across said contacts on each said vehicle, said switch alternately connecting and disconnecting said brush means for equal angular degrees of rotation, and means to rotate said switch to pass current on the same alternate half cycles substantially in phase with said devices, the output of said devices being connected with the same polarity on the same one of said conductors when said vehicles are operating in the same direction along said conductors.

44. A speed control system for two-directional operation on the same track comprising, a vehicle way, reversible self-propelled vehicles thereon, a control circuit path on each said vehicle having in series current signal supply means and means for controlling said supply means according to vehicle velocity to provide a voltage having a polarity representing which end of the vehicle is running forward and having an open circuit value representing vehicle speed, control circuit conductors connecting said paths in parallel between vehicles along said way, current direction selective control means in each said control circuit path and reverse means connected to reverse each said selective control means in a said circuit path when that said vehicle has its drive reversed and when that said vehicle is turned around and including a vehicle way located actuator, and vehicle located reverse switch means arranged to be actuated by said actuator to reverse the polarity of said signal means when the vehicle is turned around and operated past said actuator in said way.

45. In a speed control system wherein dynamos are connected across conductors between vehicles and controlled to develop a voltage representing vehicle speed, a said dynamo having its main field separately excited,

a series field wound in such a direction as to oppose the main field of said dynamo while said dynamo is generating a current to reduce the voltage of the dynamo when generating a current and to increase the back electromotive force of the dynamo when motoring.

46. In a circuit including two dynamos in series each driven and connected to provide an output voltage bucking the other and each representing for comparison a variable by the value of its open circuit voltage, a series field on a said dynamo wound in such a direction as to oppose the current generated by that dynamo to reduce the current between the dynamos.

47. A speed comparing system comprising two vehicles the speeds of which are to be compared, two tachometric generators each on a said vehicle, means for controlling said generators to provide a substantial output voltage representing the speed of a said vehicle for comparison, a circuit including running contact conductors connecting said generators so as to buck, the speed difference between said vehicles being represented by the current in said circuit, and current direction discriminating and indicating means in said circuit in series with said generators to determine which of the two vehicles is traveling faster.

48. A device to delay deceleration as long as the control current dies out sufficiently when cars come into intercontrol with each other and comprising: a relay arranged to pick up on a heavy control current and hold to a weak control current, front contacts thereon, a first shaft driven at a speed proportional to vehicle speed, a second shaft, an electrically controlled clutch connecting said shafts, circuit means controlling said clutch connected through front contacts of said relay, a rotary rheostat having its rotary portion secured to turn with said second shaft, and positioning means connected to turn said rheostat to full resistance position when said clutch is disengaged and to be driven therefrom at least resistance position by the engagement and turning of said clutch, over-current relay means and circuit means for connecting the coil of said over-current relay means in series with said rheostat to reduce the resistance in series with said over-current means as the clutch turns the rheostat, and means controlled by said over-current relay means for decelerating the vehicle when the control current is above the limit representing safe speed.

49. In combination with a device as claimed in claim 48, a self-propelled railway vehicle, reversible positive-power-transmission means connecting said clutch to turn with and at greatly reduced speed from the wheels of said vehicle, a traction power reverse switch connected to reverse said transmission, whereby said rheostat is turned in the same direction for either direction of vehicle movement.

50. In combination on a self-propelled railway vehicle, a coupling switch at each end of the vehicle having contacts forced open between coupled vehicles and closed when vehicles are uncoupled, a source of control power, a reverse switch for reversing traction power and a double-throw switch connected thereto to reverse therewith, vehicle operating means, and circuit means connecting said source of control power to said operating means in series through said double-throw switch and the said contacts of the coupling switch which is at the forward end of the vehicles as determined by the position of said reverse switch whereby the operating means at the head end of a train alone is energized to control the train.

51. In a railway control system, an intertrain control circuit including in series between any two trains therein an electromotive source for each train representing the train's speed by a voltage output increasing with the speed of the train, automatic stopping means controlled by said control circuit and polarizing means for biasing stopping operation of said stopping means to be responsive to current in said control circuit having a par-

ticular direction only, a clear track signal means and means for receiving a clear track signal therefrom for a train when the track ahead is clear and associated with said stopping means to make ineffective said control circuit from operating said stopping means for that train while receiving a clear track signal.

52. A circuit for opening the intertrain control circuit on a unit uncoupled from a train relative to the train for a time allowing the train to clear the uncoupled unit by control-line-section length as minimum, said circuit comprising in combination a power supply, a coupling switch positioned to be opened between coupled cars and closed at the head end of an uncoupled unit of cars and the coil of a time delay device in series; a relay having back contacts in series in the control circuit on the uncoupled unit; back contacts on said time delay device for opening after the time delay; and a circuit completed across said power supply and including in series said coupling switch, said back contacts on said time delay device, and the coil of said relay to energize said relay to open the control circuit on the uncoupled unit upon uncoupling until the time delay device opens said back contacts.

53. Automatic speed controls comprising in combination: a reversible pilot motor, a controller connected to be reversibly driven by said motor, power supply means, a pilot-motor reversing relay having plural front and plural back contacts, switches associated with said controller to be operated therewith and including: a first 25 opened in off position, a second opened in full speed position, and a third opened on running positions of the controller, said switches being closed in substantially all other positions of said controller, an operating relay having front contacts, a holding relay having back contacts, 30 the armature of said pilot motor being connected through front contacts of said reverse relay to terminals of said supply to accelerate said controller and through back contacts of said reverse relay to opposite terminals of said supply means in series with front contacts of said operating relay and back contacts of said holding relay, the coil of said operating relay being connected in series with said first switch across said supply means, an accelerating relay having front contacts, the coil of said reverse relay being connected in series with front contacts on said accelerating relay and said second switch across said supply means, said third switch being connected in parallel with the back contacts of said holding relay to enable the controller to return to the nearest running position when said reverse relay drops.

54. In an automatic speed control arrangement as claimed in claim 53, an operator's control switch, first and second normally open contacts thereon closed when said control switch is partway closed one being in series with the front contacts of said accelerating relay, the other being in parallel across the said front contacts 55 of said operating relay, a third normally open contact on said control switch closed in substantially full engaged position of said control switch and connected in parallel with said front contacts on the accelerating relay.

55. In an automatic speed control arrangement as claimed in claim 54, a fourth switch associated with said controller to be operated therewith opened in the running positions of said controller that can be selected by the operator, a fourth normally open contact on said control switch located to be closed after said first and second contacts close but before said third contacts close, and circuit means connecting said fourth contacts in series with said fourth switch in parallel with said third switch.

56. In a railway automatic speed control system, a notch down comprising in combination, a first series of relays each having a first coil and first front contacts, at least one stopping relay, control power supply, said first coils all being connected through contacts of the 70 stopping relays across said supply, a second series of

relays having front contacts, a series of circuit paths or notch lines each including the coil of the corresponding relay of said second series connected in series with said front contacts of the corresponding relay of said first series, second front contacts on each relay of said first series except the highest, a second coil on each relay of said first series above the first connected across said supply in series through said second front contacts of the preceding relay of that series and front contacts of the relay of the second series which is connected in series with contacts of the preceding relay of said first series whereby when said stopping relay opens its contacts to the coils of the first series of relays the relays of said first series not closing a live control circuit and the highest relay closing a live control circuit will drop together first and then the remaining relays of said first series will be deenergized in succession until the stopping relay closes.

57. Imposed in the control leads between a manual controller and multiple-unit train lines, an automatic controller, comprising a first relay means for successively closing said control leads to a source of control power upon the energizing of said relay means, means for energizing said first relay means to successively close said control lines to accelerate the train, a second relay means arranged to successively open said control lines in the reverse order that said first relay means is arranged to close them, and means for energizing said second relay means to reduce train speed.

58. In a speed control system, in combination: a track, a first and a second control circuit contact path paralleling said track and each comprising coextensive lengths of conductor and insulators separating said lengths; block circuits, each having a current supply connected across said conductors with similar polarity in each said block, and block circuit relay means connected across said conductors in each said block and each having first and second contacts controlled to open by the track circuit of that block; vehicles on said track, each having a current collector engaging each said conductor and two rectifier means connected in series across the collectors and arranged to short each control block connected; a bypass for each said insulator including a first and a second rectifier on opposite sides of each said contacts on a said relay means connected in series across each said insulator, said rectifiers being arranged to pass current from left to right along said contact paths, said first rectifiers being connected to a said conductor in the block at the left, said second rectifiers being connected to that conductor in the block at the right, the output terminal (minus side) of the said first rectifier which is connected to the minus conductor on the left being connected to the input terminal of the said second rectifier which is connected to the positive conductor on the right, the coil of the said relay means being connected across said lengths in an adjacent said block to be energized by the current supply thereof and shorted through said collectors to bridge adjacent blocks, a return conductor of said track, a control current path connected from a point between said rectifier means on each said vehicle to said return conductor and including in series electromotive means providing a voltage representing vehicle speed and having a positive polarity to said rectifier means when the vehicle is traveling from left to right and minus when from the right; and current direction detecting means connected in series in said control circuit associated with a said vehicle for control of the vehicle, and switch means having contacts connected across the said rectifier means connected to the contactor which engages the contact path to which is connected the minus sides of said current supplies for bypassing that rectifier to complete a control circuit between said vehicles when within one said block.

59. In a system as claimed in claim 58, a two coil aiding relay having both coils connected in series between

said rectifier means on a said vehicle, said electromotive means being connected in the circuit between the coils of said relay, said relay serving to indicate that said collectors are in contact and that the block circuit is shorted therethrough.

60. In a speed control system comprising a stretch of track, a train thereon having a plurality of self-propelled vehicles therein, a speed difference circuit comprising a sectionalized contact conductor paralleling said track, rectifiers connecting adjacent sections of said conductor to pass current in the same direction at the same time along said conductor, a return current path along said track, current collectors on vehicles of said train engaging said conductor, and a speed difference control circuit connection across the leading said collector and said return current path and including a tachometric device supplying a voltage varying in one direction with vehicle speed so as to represent train speed; an uncoupling circuit in said train for detaching a portion thereof at speed, conductive means connecting said collectors together on said train, switch means connected to open said conductive means between the rear and leading said collector, a relay having its coil connected across the rear said collector and the return path and having contacts in series with said uncoupling circuit to prevent uncoupling while current from a said tachometric device is passed through the coil of said relay, said rectifiers being connected to block current of the tachometric device of the forward portion of the train from said relay.

61. A speed control system which enables vehicles to safely couple and uncouple from a train at speed, comprising in combination: a length of guideway, a first and a second vehicle unit thereon, a control circuit between said units and having a first and a second current means for supplying a voltage variable with and relatively representing speed of said first and second unit respectively, circuit means connecting said first and second current means in series bucking when said first and second vehicle units are operating in the same direction on said length of guideway, and means associated with said circuit and with said units for controlling the speed difference between said units according to the current direction through said circuit.

62. In a contact system of vehicle control a vehicle way having two low impedance control current conductor means for connecting a polarized circuit between trains insulated apart and paralleling said way, at least one said conductor means being sectioned into several sections, and means electrically connecting adjacent said sections and arranged so that current can simultaneously flow in one direction in one said conductor means and return in the second said conductor means and to be blocked from flow in the opposite direction from section to section, said conductors being electrically separated except when connected through vehicle carried circuits.
